UNITED STATES PATENT OFFICE

2,363,751

WRAPPING MACHINE

Rudolph Henry Schultz and Adam James Siebert,
Brooklyn, N. Y.

Application August 3, 1940, Serial No. 351,028

12 Claims. (Cl. 93—2)

This invention relates to wrapping machines, and more particularly to wrapping machines for entirely enveloping or making an over-all wrap for cylindrical objects at high speed, such as rolls of toilet tissue, paper toweling and the like.

Objects

The objects of the invention are to provide an improved wrapping machine of the character indicated; to render such a machine fully automatic; to provide for placing a wrapper tightly around rolls of different diameters and widths by convenient adjustment of the machine; to accommodate rolls in any particular run which vary considerably from the standard diameter for which the machine is set for that run; to enable the machine to employ printed wrappers fed from the roll for long runs or individually printed and cut sheet wrappers for short runs; to maintain registration of the printing on the web wrappers with relation to cutting from the web; to avoid the use of reciprocating parts and employ such mechanism as will assure continuous smooth operation; in other words to provide a machine employing rotary continuous principles for high speed continuous operation and production; to enable wrappers of relatively light weight paper to be employed; to automatically apply adhesive at separate parts of the wrapper and adhesively affix the leading end of the wrapper to the rolls, and adhere the trailing end of the wrapper to itself after encircling the roll; to automatically crimp the wrapper around the ends of the rolls and automatically tuck the edge of the wrapper into the core of the rolls; to provide improved mechanisms for feeding, handling and applying the wrappers automatically and for feeding, handling and discharging the rolls fully wrapped; to provide a machine which can be constructed and shipped in units or otherwise and set up for initiating operation thereof; to render such a machine fully automatic; to provide sheet feeding mechanism whereby individual printed sheet wrappers are fed from a stack, the sheet feeding mechanism being adjustable for handling sheet wrappers of such width and length to properly overall wrap the various size rolls for which the machine can be adapted; the printed sheet wrappers are for use on short runs or small orders; to provide for employing printed wrappers in roll form for long runs; to maintain registration of the printing on the web wrappers through electric eye control with relation to cutting from the web; to make provision to accommodate wrappers in roll form of various widths

and to provide severing mechanism for cutting wrappers of varying length from the web to suit the product to be wrapped; to apply adhesive to the leading and tail ends of either the sheet wrapper fed from the label feeder or to the wrapper web cut from the roll; to adhesively affix the leading end of the wrapper to the roll to be wrapped at the point where the feeding wrapper and traveling and rotating roll meet in timed relation to each other; to adhere the trailing end of the wrapper to itself after encircling the traveling and rotating roll; to crimp or gather the overhanging ends of the wrapper for tucking into the core of the traveling roll and to make provision for removing the overall wrapped traveling roll from the equipment for boxing and shipment; to provide a conveyor in which a series of wound rolls from several rewinders that produce these rolls are deposited; these rolls incidentally produced on the several rewinders contain the same amount of material but due to varying rewind tensions employed on the rewinders and due to the caliper of the paper varying slightly the rewound rolls produced on the several rewinders vary considerably in diameter; it is essential that the wrapping equipment be flexible to handle these varying diameter rolls and place wrappers tightly around them; the conveyor is of considerable length and may be power driven by the wrapping machine or by an independent motor as illustrated in the accompanying drawings; to secure simplicity of construction and operation; and to obtain other advantages and results as may be brought out in the following description.

Drawings

Figure 1 is a side elevation of a wrapping machine embodying our invention;

Figure 28 is a detail elevation partly in section of certain clutch mechanism shown on the left of Fig. 25;

Figure 29 is a view similar to Fig. 26 but on larger scale and less extensive;

Figure 30 is an elevation looking at the front edge of the mechanism shown in Fig. 29 and on the same scale, the same mechanism being shown in somewhat less detail and on a smaller scale at the upper left hand part of Fig. 25;

Figure 30A is an enlarged sectional view of the differential mechanism;

Figure 31 is a plan of the portion of the mechanism shown in Fig. 29 except that the

bracket, magnet and associated parts shown above the ratchet in Fig. 29 are omitted;

Figure 32 is a detail sectional view of the commutators and electric contacts shown in elevation on the left hand end of Fig. 33;

Figure 33 is a sectional view substantially on line 33—33 of Fig. 29;

Figure 34 is a schematic view of mechanism and circuit arrangement for the control by the electric eye and phototroller employed for maintaining adjustment of the web feeding with the cutting mechanism;

Figures 35 and 36 are further schematic showings of the control of the web by the electric eye directed upon recurring marks on the web;

Figure 37 is an end view of the roll holding, roll wrapping and wrapper crimping and tucking mechanism shown on smaller scale and in less detail at the right hand of Fig. 1, the present showing being substantially a sectional view on line 37—37 of Figure 2;

Figure 38 is a view similar to Fig. 37 lettered to indicate operations and functions occurring in the mechanism at a given position thereof;

Figure 39 is a vertical diametric sectional view of the mechanism shown in Fig. 37;

Figure 40 is an enlarged detail view of the portion of the mechanism shown at the right of Fig. 38 where the wrapper is applied to the roll and caused to encircle the roll;

Figure 41 is a plan of the portion of the mechanism shown in Fig. 40 controlling the final delivery of the wrapper to the roll;

Figure 42 is a detail sectional view as upon line 42—42 of Fig. 44 of the roll supporting, wrapper crimping and wrapper tucking mechanism;

Figure 43 is a sectional elevation as upon line 43—43 of Fig. 42;

Figure 44 is an elevation of the portion of the mechanism shown in Fig. 42;

Figures 45 to 48 are sectional elevations showing the successive steps of crimping and tucking the wrapper;

Figure 49 is a sectional view on line 49—49 of Fig. 47;

Figure 50 is an enlarged sectional view showing the roll mounting and wrapper tucking mechanism in its position tucking the wrapper in a roll;

Figure 51 is a detail sectional elevation of the means for gripping a roll by its periphery while the roll holding and tucking mechanism is moving out of the core from its supporting position and back into the core for tucking the wrapper;

Figure 52 is an elevation of the portion of the mechanism shown in Fig. 51; and partially in section on line 52—52 of Fig. 51;

Figure 53 is a sectional view on line 53—53 of Fig. 51;

Figure 54 is a plan of the mechanism for feeding the rolls to the wrapping machine;

Figure 55 is a plan of the feed channel for the rolls from which the rolls are transferred to the wrapping portion of the mechanism;

Figure 56 is a side elevation of the portion of the mechanism which receives the rolls from the channel of Fig. 55 and showing the mechanism for advancing the rolls in timed relationship to the wrapping mechanism;

Figure 57 is a view looking at the left end of Fig. 56 and also showing the feed channel and associated mechanism for the rolls in sectional elevation;

Figure 58 is a sectional view substantially on line 58—58 of Fig. 56;

Figure 59 is a sectional view substantially on line 59—59 of Fig. 56;

Figure 60 is an elevation of the Geneva motion control and driving mechanism in the transfer rotor;

Figure 61 is an edge view of the mechanism shown in Figure 60;

Figure 62 is a detail sectional elevation of a holder mechanism forming part of the means for feeding the rolls to the transferring mechanism of Fig. 59;

Figure 63 is a sectional view crosswise of the feed channel and showing clutch mechanism and brake for holding the rolls back periodically from traveling forward in the feed channel;

Figure 64 is a longitudinal sectional view through the clutch and associated parts;

Figure 65 is an elevation of the outer right hand portion of Fig. 64; and

Figure 66 is a sectional view on line 66—66 of Fig. 64.

In order to more clearly understand the need for the several constructions employed in the wrapping equipment it is necessary to know the manner in which the rewinding equipment functions and following is a slight description of how the rolls to be wrapped are produced.

As stated above a series of rolls are produced at one time on the rewinding equipment in the following manner. A wide mill or parent roll of paper is placed in the rewinding machine, the web of which is fed through this machine where it is perforated, slit and rewound on to small cores, the width of the slit ribbons, carried on a rewind spindle or shaft. After a predetermined amount of material has been rewound the web is severed and the series of rolls removed from the spindle and deposited in the conveyor of the wrapping machine.

However the following must be considered as concerns these rolls that have been deposited in the conveyor.

The tail ends of these rolls in some instances have adhesive applied to them either manually or mechanically in the rewinding machine or the adhesive may be applied after removal from the rewinding machine and before depositing in the conveyor, or the rolls may be deposited in the conveyor without having adhesive applied but regardless if they have or have not adhesive they must be placed in the conveyor always one way so that when the rolls feed into the wrapping machine and the wrapper is placed around the roll, the roll in rotating will have a tendency not to unwind itself but to keep itself wound up.

After the spindle is removed from the series of rolls, the rolls are manually deposited in the conveyor in the same relation to each other as they had on the spindle. However, these rolls in the majority of instances are interlocked with each other where they are slit and must be broken apart by the wrapping equipment; further, the several slit webs may not line up perfectly with the cores so that the cores partially project into the next roll; also as the rolls are rewound they may cone—that is, they do not build up straight on their sides. These conditions must all be corrected in the wrapping equipment. In addition it must also be remembered that in a great many instances the rolls are soft being very loosely wound and therefore not very round.

The conveyor consists of a belt substantially the width of the largest diameter roll that the

wrapping unit can accommodate. The belt in turn resting on a table from which extend uprights substantially in height the diameter of the largest roll, thus making a trough for the belt and rolls to rest in. The rolls are placed in the conveyor for its entire length end for end. This conveyor belt with the rolls thereon moves intermittently in timed relation with the wrapping equipment. The conveyor full of rolls is carried forward, the leading roll on the conveyor sliding on a pin positioned at this point in line with the hole in the core of the roll. The roll is prevented from going any further on the pin but just so far by means of an actuated stop. If the roll happens to be coned it is straightened out on encountering this stop and if the core happens to project it is forced into the roll. After this roll is so positioned on this pin due to the roll being forcibly pushed on the pin by the frictional pressure of the following rolls on the conveyor acting on this roll, the conveyor comes to rest at which time several mechanisms operate as follows more or less simultaneously. The pin on which the leading roll on the conveyor has been pushed is carried in a hub that mounts additional pins spaced 90 deg. from each other. At the moment the roll has mounted the pin and the conveyor comes to rest this hub operates moving the roll mounted on the pin through an arc of 90 deg. or the roll from lying in a horizontal position assumes a vertical position. The hub at this time comes to rest presenting another pin on which the following roll mounts as the conveyor again operates to feed the rolls resting thereon.

However just at the point where the hub starts moving the pin with the roll on it, the actuated stops that have prevented the roll from moving further on the pin drop away from the roll. It will be seen that now this roll has a certain amount of freedom allowing it to slide on the pin. Before the actuated stops dropped away from the roll this roll was tightly wedged between the actuated stops and the following roll and if the stops were not released this pressure would be such as to mangle and smash the roll on the pin and one or more following rolls. It will now be seen that the reason for intermittently driving the conveyor and having the actuated stops is for the purpose of releasing this pressure and to facilitate the removal of the roll on the pin from the conveyor.

As the hub again moves through an arc of 90 deg. the roll mounted vertically on the pin is again positioned horizontally some distance away from the rolls resting on the conveyor but in the same line and plane with them. This roll is now removed from this pin by means of a stripper that acts in timed relation with the hub. The roll is ejected from the pin while the hub remains at rest and moves in a horizontal direction between a lower stationary table and a yieldable upper presser plate, the roll being stopped in its horizontal travel by means of a stop. This roll is removed from between the lower stationary table and upper pressure plate by mechanism that will be described in a later paragraph.

Incidentally the purpose of moving the roll through an arc of 180 deg. by means of the intermittently operating hub carrying the pins spaced 90 deg. from each other is to so position the rolls in this instance so that as the wrappers are placed around them they will have a tendency to wind up instead of unwinding due to the reason that if the rolls were fed into the wrapping unit as they are placed into the conveyor with-

out going through this arc of 180 deg. they would unwind. The rolls cannot be placed correctly in the conveyor due to the placing of the several rewinding machines and due to the fact that it would be awkward to position them correctly without entailing loss of operating time.

In a preceding paragraph, it has been stated that at the moment the roll straddles the pin and the conveyor comes to rest several mechanisms operate more or less simultaneously at this time. Immediately the hub operates to move the pin and roll mounted thereon through an arc of 90 deg. the actuated stops release the pressure of the following rolls bearing against the roll on the pin.

As soon as this pressure is released operating arms or fingers hit a number of the rolls resting on the stationary conveyor a sharp blow at the line where the rolls are slit; this blow tending to break the interlocking rolls apart. These arms operate each time the rolls and conveyor come to rest and when the end pressure on the rolls is released so that the same roll receives several blows due to another arm striking it a blow as the conveyor with the rolls intermittently progresses so that the rolls are broken apart by the time the leading roll straddles the pin in the hub removing the roll from the conveyor.

It also happens on occasion that the rolls on the conveyor are not replenished due to the wrapping machine operating at a higher speed than the combined winders. At a point where the number of rolls on the conveyor is insufficient to forcibly push the lead roll all the way on the pin in the hub and up against the actuated stops the wrapping machine automatically shuts down due to a feeler finger riding on top of the rolls dropping down to breaking contact similar to operating the stop button on the wrapping machine. The wrapping machine will not start until this finger is raised by rolls replenishing the conveyor supply.

Going back to where the roll that has been stripped off the pin in the hub and is now held on the lower stationary table and the upper pressure plate. This roll is removed from this position in timed sequence so not to interfere with the following roll removed from the pin by means of the stripper.

This roll is now removed from its position but not in the direction in which the stripper removed it from the pin but in a horizontal plane at right angles to this direction; in other words, it moves in a direction at right angles to the way it moves and lays in the conveyor trough. This is accomplished by means of two parallel chains moving in this right angle direction and carrying between them at evenly spaced intervals plates fastened to each one of the chains. The plates are of such height and width that the lower portion clears the table on which the roll rests—the upper portion clearing the presser plate. These chains are constantly in motion and the rolls stripped from the pins are ejected on the table and presser plate between two of the plates mounted on the moving chains. As the following plate contacts the positioned roll it pushes the roll out from the stationary table and presser plate at right angles to its former path of travel. The stationary table on which the roll rests is mounted between the chains. As soon as the plate between the two chains has removed the roll from the table it lays on a fast moving belt that carries it in the same direction as the plate fastened to the chains—this plate speed being

synchronized and moving in timed relation to the chucks mounted in the constantly rotating drum. It will be observed that the chains carrying these plates at evenly spaced intervals and the fast moving belt mounted between the chains both travel in the same direction, that the following plate removes the roll from the stationary table and the leading plate acts as a stop or gauge for the roll after the fast moving belt has carried it up to this leading plate and keeps it frictionally engaged therewith. It is necessary to use a type of construction as outlined above due to the speed at which this equipment operates.

15 Adjustable side guides keep the roll so positioned as it moves from the stationary table while resting on the fast moving belt that it keeps in contact with the forward stop plate carried between the two chains so that it remains so positioned to allow the chucks contained in the drum 20 that are actuated toward each other to project into the hole in the core of the roll.

It will be seen that the roll is carried against the leading plate carried in both chains by the fast moving belt on which the roll rests; the belt holding the roll in this position by traveling faster than the plate by frictional contact with the roll; also that the roll is so positioned by means of adjustable side guides to allow a set of chucks in 30 co-alignment in the constantly rotating drum to project into the hole in the core on either side of the roll. A roll is held against each plate carried in both chains by the fast traveling belt, each plate bringing a roll in co-alignment with a set of chucks in the constantly rotating drum due to the chain speed being synchronized with the chuck speed.

40 The chucks are yieldably urged toward each other for projecting in both ends of the hole in the core. At the point where the chucks pick up to roll, the plate carried by the chains dips and goes around suitable sprockets with the chain allowing the roll to follow its rotary path in the drum. It will be noted that the chucks are 45 tapered and the nose or point of the chuck is made considerably smaller than the hole in the core of the roll—to allow the chuck to enter the core without mangling the roll due to hitting the side of the roll should the roll vary from the size 50 for which the equipment at this point is set. It will further be seen that heads slightly smaller than the outside diameter of the roll are carried on the small entering chucks; these heads engage the side of the roll straightening out any remaining cone that the roll may have initially had besides locating the core properly in the roll side-wise in the event that it projects. These same heads at a certain point in the rotating drum rotate and due to being yieldably held against the roll rotate the roll; this is at the point where 55 the wrapper is applied—due to the roll being loosely wound if it were rotated by means of the chucks that are projected into the core, the several loose winds would tighten up on themselves without the periphery of the roll rotating; therefore the heads that bear against the side of the roll are employed for this purpose in conjunction with the chucks.

60 It will now be seen that the roll is located in the constantly rotating drum by means of the chucks entering the hole in the core on either side of the roll and that heads slightly smaller than the diameter of the roll yieldably bear against the sides of the roll. The drum carries 65 a certain number of sets of chucks and heads

and each set on the continued rotation of the drum picks up a roll from the conveyor which carries rolls in timed relation to the chucks and heads carried in the drum.

As mentioned above the drum rotates continuously each of the stations picking up a roll. These rolls are carried by the drum in its rotary travel and a wrapper placed on the roll—all of the operations of completely overall wrapping of the roll on a partial revolution of the drum—the wrapped roll then being ejected and the chucks on their continued rotation again picking up a roll from the conveyor for wrapping. A construction of this type is employed to secure high speed operation and production—all operations of placing the overall wrapper around the roll being made during continued rotation of the drum.

As stated above this rotary mechanism lends itself to high speed operation as several functions are performed on the rolls carried in the drum simultaneously. If all of the operations were performed at one point of overall wrapping the roll the advantage of production speed would be lost. The several steps required for placing the overall wrapper around the roll as the drum rotates and the sequence of operation are important.

After the chucks which are mounted on shafts in the constantly rotating drum enter into the core of the roll carried on the moving conveyor and remove it from this conveyor—the roll is carried downwardly and then again upwardly to a point where gears mounted on each one of the shafts from which the chucks are mounted will yieldably hold the roll by means of the chucks and heads. The above gear on this shaft as the drum rotates engages a stationary rack radially mounted to the drum frames. It will be seen that continued rotation of the drum—with this gear in mesh with the stationary rack will rotate the gear—chuck shaft—and the chucks and heads and in turn these rotate the roll that is yieldably held between them. This radial rack is of such length that it will continue to rotate the roll held in the chucks, this is the function of the rack, to allow a wrapper that is adhesively affixed by its leading end to the roll to completely overall wrap it. This operation will be explained in more detail in a later paragraph. At the point where the roll starts to rotate by the gear engaging the stationary radial rack, the top portion of the roll engages a roller that it here contacts as the drum carries the roll through its orbital path.

As stated above, the gear that is mounted on the ends of the chuck shaft engages with the stationary radial rack. It will be noted that it is essential to provide mechanism whereby the teeth of this gear engage correctly with the teeth of the radial rack. This mechanism consists of a square block that is fastened to one face of this gear and also mounted on the chuck shaft. This square block in the orbital path of the chuck shaft engages a spring urged latch or pawl. The purpose of this latch or pawl is to position the square block so that this square block will slide along a stationary radial track. Due to the relationship of the sides of the square block that slide along this stationary radial track with the teeth in the gear, the teeth of the gear will mesh properly with the teeth of the rack. At the point of engagement of the teeth in the gear with the teeth in the rack, the stationary radial track stops, so that as the gear and square block rotate the corners of the square block cannot interfere with this stationary radial track.

This presser roller is journaled in yieldable bearings in levers fastened to a shaft that is cam operated. Also fastened to these levers is a guide table along which the wrappers with adhesive on their under leading and tail end are fed by feed rollers contained in the pasting section. These wrappers feed along the guide table consisting of supporting strips between the broken paste line on the wrapper—so that the adhesive does not contact these strips or guides as the wrapper is propelled by the feed rollers or discs underneath the presser roller—this top portion of the wrapper tangentially contacting the under periphery of this roller.

15 The wrapper and the roll of tissue in the drum and the presser roller all meet in timed relation. The roll at this point is rotating while traveling in its orbital path, the wrapper as it feeds along the guide table at this point tangentially feeds on the top part of the roll between the presser roller and the roll. As the roll continues in its orbital path still rotating the cam actuated presser roller and guide table follow the roll by the levers holding both the roll and guide table oscillating on their cam operated supporting shaft. The presser roller is frictionally driven by contacting the roll and the wrapper due to feeding between the roll and presser roll is affixed to the roll by the strip of adhesive on the leading end of the wrapper.

20 As this roll continues to rotate and also travel along its orbital path the wrapper is placed around it and affixed to itself by the adhesive at its tail ends. It will be noted that even if the roll varies in diameter it is tightly wrapped around the roll due to the action of the presser roller. At the point where the wrapper is affixed to itself the presser table and roller fall back to their inoperative position to allow the next wrapper to feed along the table for placing around the following roll as it contacts the presser roller and the operation as above is repeated.

25

30 At the point where the leading end of the wrapper is adhesively affixed to the roll by the action of the presser roller—the feeder rollers that have fed the wrapper to this point release the wrapper—as it now travels at a rate of speed greater than the feed rollers that have delivered it to this point.

35

40 The wrapper is now affixed to the roll, a considerable portion of the wrapper overhanging both sides of the roll and the roll continues along its orbital path in the constantly rotating drum to have the next operation performed on it.

45

50 Carried on the drum shaft and so positioned in relation to the several sets of chucks and rolls are grippers or jaws in an open position in line with the several rolls positioned in the chucks in the rotating drum and rotating in fixed relation with them.

55

60 At the point where the wrapper has been placed around the roll and the roll stops rotating on its axis but is still carried in the rotating drum the jaws or grippers close around the roll and the chucks and heads are withdrawn from the roll.

65

At this point fingers tend to operate on the overhanging ends of the wrapper crimping or gather them for tucking into the core of the roll.

70 These tucking fingers operate radially from the chuck spindle center carried in heads mounted on these spindles, the heads acting as bearings for the chuck spindles. The heads are carried on studs or rods carried in the drums and can be moved laterally to accommodate varying width rolls.

75

As stated above, the tucking fingers operate to close on the overhanging portions of the wrapper through suitable cam mechanism to crimp or gather the wrapper so that it can be picked up by the chuck noses for placing into the core.

It will be noted that between the tucking fingers carried in each head are rods pivoted and slidably mounted in the fingers to comb all of the wrappers toward the point where it can all be gathered by the chucks for placing in the core of the roll. If these rods were not employed portions of the wrapper would not be brushed to the center of the roll and ears would project making a poorly wrapped roll.

At the point where the tucking fingers have closed and gathered all of the wrapper for tucking into the core the chucks and heads again operate moving toward the core in the roll—the crimped wrapper is picked up by the hollow chuck nose and at this point the tucking fingers open and the chucks plunge the wrapper into the core—the heads acting to flatten it closely against the face of the roll.

After the chucks and heads have laid the wrapper in and against the sides of the roll they again withdraw. The grippers or jaws still hold the roll and have held it through all the preceding operations as the roll continued in its orbital path in the constantly rotating drum.

Due to a light paper wrapper being employed it is necessary to perform the tucking or crimping operations slowly, otherwise in crimping quickly the wrapper would be torn. For the above reason it is necessary to employ a drum and rotary mechanism to produce a high speed machine turning out a perfect product. The rotary drum allows the crimping action to be performed slowly—this being impossible if the wrapping were all performed at one station.

After the roll has been completely wrapped it continues in its orbital path to such a point to where the grippers or jaws release it to an inclined runway for boxing and shipment. The grippers and jaws remain in the open position until such time where they again grasp the overall wrapped roll that is carried in its related set of chucks—these chucks remain withdrawn until such time as they again are yieldably urged toward each other for removing a roll by its ends from the traveling conveyor. It will thus be seen that all operations are performed while the roll is constantly traveling lending itself to a high speed production of 90 wrapped rolls per minute or better.

Provision has also been made at the point where the grippers release the roll to the inclined chute for a trap door in the inclined chute as it on occasion happens that the rolls are not removed from the inclined chute quickly enough and pile up to such a point that as the following grippers in opening to release a roll encounter a full chute—the leading following gripper then forces the roll lying on the trap door through where it falls to the floor or a suitable receptacle without damage resulting to the equipment and without holding up the operation of the equipment until such time as the offending rolls on the chute are removed.

As stated in the beginning of the description, wrappers are fed to the roll held in the constantly rotating drum either from a sheet feeder or from a roll. These wrappers having adhesive applied to their under leading and tail ends.

In respect to the wrappers that are fed forward by the sheet feeder, this sheet feeder is so con-

structed that a stack of several thousand printed wrappers of suitable width or length can be placed on the sheet or label feeder table. The height of the top wrapper of this stack always remains constant due to suitable mechanism that tends to elevate the table on which the stack of wrappers is placed. This top wrapper is of such height that it is intermittently engaged in timed relation with the rest of the mechanism by combing rollers that drop on this top wrapper and feed it forward between several pinch or feed rollers. The wrapper is then carried forward by these feed or pinch rollers on to a series of traveling belts. While resting on these belts it is jogged or gauge sideways so that both overhanging ends of the wrapper as they encircle the roll will be of the same length. The traveling belts with the wrapper resting on them carry it forward to a point where projecting stops hold the wrapper stationary against the frictional force of the belts. The stops have two purposes. One to allow the wrapper to enter the mechanism in exact timed relation with the pasting and the roll carrying arrangements and also to make certain that the leading end of the wrapper is square. In other words, the belts comb the wrapper against the stop, and the stops straighten it out so that the leading end of the wrapper feeds forward after the stops are depressed so as to contact the roll around which it is placed in a straight line. This wrapper after the stops release it feeds forward to such a point where the leading end is depressed and contacts paste discs that deposit a series of strips of adhesive laterally across the bottom of the wrapper. The tail end of the wrapper has adhesive applied in a similar manner. The wrapper is propelled or fed forward from the point where the stops release it between a series of pinch rollers along strips or guides. These guides at the point where the leading and tail ends of the wrapper are depressed are pivotally mounted so that as the rubber roller cam actuated contacts the moving wrapper, this roller presses the wrapper down on the several strips or guides and also depresses these guides that are spring urged into their inoperative position. The guides and the wrapper are depressed until the wrapper contacts the paste discs which are spaced somewhat below the top of the guides and the feeding wrapper. As the roller again releases the wrapper and the guides, the guides being spring urged tend to lift the wrapper from the paste discs. The above operations are all performed while the wrapper is in motion. The feeding wrapper is then conveyed forward to such a point where it feeds between the roll and the presser roller and the leading end of the wrapper adhesively affixed to the roll.

In respect to the operation of the roll fed wrappers, this is a roll of appropriate width to overall wrap the roll for which the equipment has been set. This roll has at spaced intervals printed designs on it. It is necessary to sever the web between the printed designs and to always make certain that the register between the printed designs and the cut-off is such that at no time will the severing take place in the middle of a printed sheet but always between the printing. The mechanism can also be set by means of change gears to feed a predetermined amount of wrapper to suit the object to be wrapped. This predetermined amount of wrapper will vary depending on the diameter of the roll in question that must be wrapped. Incidentally, through change gears and electric eye control, this wrapper web is fed

and cut-off in timed relation to the rotating drums containing a series of rolls to be wrapped. After the wrapper has been severed from the web it feeds in a downward direction by means of feed rollers and supporting guides around a drum or cylinder on to the guides along which the wrapper from the label feeder also feeds and adhesive is applied to this wrapper in a similar manner as to the wrappers that originate from the label feeder. The sheet wrapper cut from the web also has adhesive applied to its under leading end and tail end and it is fed forwardly to such a point where it engages and is affixed adhesively to the roll around which it will be wrapped with mechanisms as explained in preceding paragraphs. Adhesive is applied to tail end and the leading end of the wrappers by means of paste discs contained in paste pots. A series of discs contained in one paste pot for placing adhesive on the leading end of the wrapper and another series of discs contained in another paste pot for placing adhesive on the tail end of the wrapper. These paste pots are carried by means of a rack and pinion and crank control on elevators so that the paste pots can be elevated into position and driven from these elevated positions in time relation with the wrapper feeding mechanism or at the end of a day's run can be lowered and removed from the equipment for cleaning.

The entire mechanism as explained in the preceding paragraphs is all synchronized as to operation and feeding of the different units so that they all meet in timed relation to make an operative high speed wrapping machine for overall wrapping of rolls or similar articles. The above is a general description of how this machine functions. Following will be given a more detailed description of how the various units operate.

The machine for sake of clarity will be divided into sections whereby the following description may be understood in continuity respecting the several mechanisms.

A. The conveyor carrying the rolls from the rewinders to the point where they are ejected from the pin in the rotary hub.

B. The conveying means that carries the roll after it has been ejected from the pin to where it is grasped by the chucks and the drum.

C. The drum and all mechanisms for affixing the wrapper to the roll and ejecting the wrapped product from the equipment.

D. Pasting section.

E. Label feeding section.

F. Roll feed unit.

Entering now upon a more detailed description of the drum and mechanism section A, and having reference to Figures 37 to 53 inclusive, it will be observed that between suitable side standards or housings 75, 75 is located a rotor comprising various mechanisms mounted upon a shaft 76 extending crosswise of the machine and suitably journaled in said housings. As part of the rotor, and as shown in Fig. 39 is a drum 77 midway of the housings secured upon the shaft to rotate therewith. In section A and at opposite sides of the drum and also mounted on the shaft to rotate therewith are spoked members here referred to as spiders 78, 78. The shaft, drum and spiders rotate continuously and simultaneously and the path of rotation of the periphery of the drum represents the orbital path of movement or revolution of the rolls of paper 79 or other articles to be wrapped since the rolls of paper are situated, during the wrapping operation, at the periphery of the drum. The drum and spiders are

adapted to successively receive rolls 79 next the bottom position of the drum and spiders and carry said rolls through an orbit forwardly upward and then rearwardly toward the back part of the drum and spiders and discharge them completely wrapped. There are accordingly, several rolls 79 carried by the rotor at one time and having successive operations performed during the transition through the orbit of movement. As here shown, there are provided eight means for mounting rolls in the rotor, and seven rolls are carried at one time, the eighth mounting means passing from the discharge position to the re-loading position as shown in Fig. 37. The transition from one position to the next is a continuous motion and therefore definite reference to the positions in this description covers the latitude of motion while the operation proceeds.

20 By means to be subsequently described, the roll is brought to the periphery of the drum at a bottom part thereof with the axis of the roll parallel to the axis of the drum. The spiders have studs which are movable parallel to the axis of 25 the drum and in substantial alignment with the axis of the positioned roll. Means are provided for projecting the studs at opposite sides of the roll, toward the roll and into the opposite ends of the core 80 thereof. The roll at the bottom of Figures 37 and 39 is shown to be thus supported.

The detail construction of the stud mounting for the rolls of paper will be found illustrated in Figs. 42 and 43 more particularly. In said figures, each mounting means preferably comprises a stud shank 81 rotatably and slidably mounted in an outer or peripheral part of the spider so as to be slidable parallel to the axis of rotation of the spider. At the inner end of said shank 81 is a stud head 82 of proper dimension and taper for readily entering the end of the roll core 80. On said head 82 may be mounted or otherwise constructed a flange member 83 the inwardly directed face of which will engage against the end of roll 79 when the stud head is forced into core 80. Frictional contact of the stud head 82 and flange 83 with the roll obtains the desired gripping of the roll and will result in the roll rotating with the stud head and flange at such time as those parts are caused to rotate, as hereafter described. At the time said roll is initially engaged by stud head 82 there is no rotation of the stud head taking place, but only a lateral transition caused by rotation of the drum and spider.

55 55 Mounted upon the stud shank 81 toward the outer end thereof and on the outer side of the spider 78 is a shift collar 84 beyond which is a pinion 85 and therebeyond a square or other suitable knocker-block 86. Said shift collar, pinion and knocker-block are fast with respect to each other and to the shank. Longitudinal movement of the shank is effected by ends of a forked arm 87 riding in the groove of the shift collar, said arm being pivoted at 88 (see Figs. 39, 44 and 54, 60 particularly) on a bracket 89 projecting at the outer side of the spider. Said arm is a first class lever with the far end having rollers 90 thereon and also having a rod 91 pivoted thereto, said rod also extending through the spider parallel to the shank and carrying a spring 92 on the rod which normally presses the rod toward the arm and thus impel the shank normally to its inward or roll-engaging position.

A suitable track cam is provided for engagement with said rollers 90 of arm 87, and as here

shown (see Fig. 3 particularly) said cam track is formed in sections bearing reference numeral 93 (with exponents). At the moment of arrival of the stud shank at the roll pick-up position, arm 87 is held swung by cam track section 93' so the roll will enter between opposite shanks. Then the rollers drop from the end of said section 93' as a result of which springs 92 actuate the shanks toward each other, forcing stud heads 82 into core 80 of the roll, to carry the roll about the orbital path to the next stage of operation.

At this next stage of operation, the forward edge of a wrapper 94 is presented to the roll, and the roll is rotated on its own axis while continuing to revolve about the axis of the rotor (see Fig. 40). At this stage, the shanks 84 are preferably positively held pressed inward towards the roll by engagement of the rollers 90 with a second cam-track section 93'' (See Fig. 3). During substantially the same period, pinion 85 is brought into mesh with a fixed arcuate rack 95. In order to assure initial meshing of the pinion with the rack, knocker-block 86 engages a protuberance 96 (see Fig. 40) which necessitates the block to ride with an edge of the block tangent to the arc of movement thereof, thereby also holding the pinion to a corresponding predetermined position so a tooth of the pinion is projecting properly to engage the first tooth of the arcuate rack. Said protuberance 96 is so positioned that it ceases to engage the block substantially at the time of meshing of the teeth of pinion and rack, and continued advancement of the pinion with the rotor causes the pinion to be rotated on its own axis. The length of the rack is proportioned to the diameter of the pinion to thereby rotate the pinion, shank and roll slightly more than 360°. Consequently the advanced edge of the wrapper is drawn by the roll and the wrapper caused to entirely encircle the roll with the trailing edge of the wrapper superposed upon the forward edge or margin thereof.

As a mechanical refinement in the engagement and operation of the knocker-block, we have shown a spring actuated trigger 97 with protruding lip 98 situated in the path of movement of the block immediately in advance of the protuberance 96. The block engages the trigger and swings it as the block advances with the lip of the trigger ultimately engaging a corner of the block next protuberance 96 as shown in dotted lines in Fig. 40. Then, further advancement of the block results in the engaged corner acting as a fulcrum to rotate the block so its forward face swings into flatwise engagement with protuberance 96. This turning of the block releases the retention by the trigger and the block then slides along the protuberance until the pinion has meshed with the rack, as shown in full lines in Figure 40.

The next operation performed upon the roll after winding the wrapper thereon, is to grip the roll by its peripheral face and release the stud heads from engagement with the core of the roll. It will accordingly be observed by reference to Fig. 3, that the rollers 90 on the shank-shifting arm 87 pass off of the second section 93'' of the cam track and go into engagement with another or third section 93''' of the cam track, this section sloping toward the spider and swinging said arm to slide the said shank outwardly. At the same time, means are functioning to close peripheral grippers 99 upon the periphery of the roll. While the said peripheral grippers may be seen

in whole or in part in various figures of the drawings, and their cycle of operation particularly shown in Figures 37 and 38 the detail structure thereof is best illustrated in Figures 51, 52 and 53, which will now be described.

The drum 77 provides at its periphery projecting lugs 100 the center line of each of which is radial with respect to the drum and each of which center lines will intersect an axial center line of the aforementioned stud shanks. The outer end of each said lug, will therefore be closely adjacent to the roll carried by a pair of stud shanks 81. Secured in the outer end portion of each lug 100 and projecting therefrom in a direction parallel to the axis of the drum is a pivot pin 101. Pivotally carried by said pivot pin 101 is a pair of gripper arms 102. One of these arms extends from the lug at an opposite side from its center line from the other arm so that, as found in Fig. 51, one arm will extend above roll 79 whereas the other arm will extend under the roll. Forward portions of the arms away from the pivotal support are made arcuate and are widened out in a direction longitudinal of the roll for affording a considerable bearing surface with respect to the periphery of the roll. Preferably, these arcuate portions of the arms each have a flexible and resilient facing, here shown as comprising an arcuate spring steel or other suitable jaw 103 the concave face of which is provided with suitable lining 104, of rubber or other soft material. It is likewise preferable to provide for adjustment of the jaw with respect to the arms for accommodating rolls of somewhat different diameters. As here illustrated, the jaws 103 are shown riveted midway of the length thereof, as at 105, to the widened portions of the gripper arms. Near the outer ends of the widened portions of the gripper arms are situated set screws 106 which can be screwed into press against the flexible resilient jaws 103 for flexing the ends of said jaws inward and in effect reducing the radius of curvature of the jaws to suit conditions of use.

As illustrated in Fig. 51, the gripper arms and jaws can be swung to the position shown in dot and dash lines for entirely clearing the jaws from engagement with the roll and entirely out of the path of movement of the roll while being introduced into or discharged from the machine. In order to operate the jaws from one position to the other, we preferably pivot bell crank levers 107 on pivot pin 101 between the two gripper arms 102, 102 on each pin. Each bell crank 107 is arranged to operate the gripper arm next to which it is situated. Accordingly, the gripper arm which extends under the roll has an arm of the bell crank next to it extending downwardly adjacent the gripper arm, whereas the gripper arm which extends upwardly with respect to the roll has an arm of the bell crank next to it extending upwardly adjacent said gripper arm. The mentioned ends of the bell crank next the respective gripper arms have a lost motion engagement with said gripper arms. As herein shown, each gripper arm has a slot 108 therein, the center of curvature of said slot being the axis of the pivot pin. A bolt 109 is shown passing through each slot into the adjacent end portion of the bell crank arm. The arms of the bell crank just described, for better identity, may be termed the operated arm. The other end of each bell crank arm beyond the pivot may be referred to as an operating end of the arm. To each of these said operating arms of the bell cranks are pivoted links 110, 110 which extend

in a direction toward the axis of the drum and attach through a suitable swivel means 111 to a slide bar 112. Said bar is shown as held to a spoke of the drum by cleats 113 so as to have a position which is radial with respect to the drum and a movement confined to the radial direction. By sliding the said bar 112 radially outward, pressure is exerted through links 111 upon the bell cranks, which in turn swing the gripper arms into position juxtaposed upon the roll, thereby gripping the same. The gripper arms are preferably normally actuated by a spring 114 to their open position. Said spring is here shown as situated upon a rod 115 parallel to slide bar 112, said slide bar having a foot 116 at its inner end to which said rod is attached. Outer end of the rod slidably passes through a knob 117 on the drum and the rod has a dog 118 situated thereon for engagement of one end of the spring, said spring being situated between said dog and knob so as to normally be under compression. Inward movement of the slide bar may be limited, if so desired, by an adjustable screw 119 shown mounted in a lug 120 on the side of the bar in proper relation to one of the cleats 113 so that the end of the screw will engage the cleat and thus limit inward movement of the bar notwithstanding the force supplied by the spring.

In order to close the gripping jaws at the appropriate time, said bar is also shown having a roller 121, thereon riding upon a cam track 122. This track may be made of appropriate length and shaped for engaging the roller and operating rod and gripper arms during the period it is desired to close said arms. In Figs. 37 and 38 we have indicated the cam track as extending entirely around the 360° orbital movement, although this might be otherwise arranged if desired.

As soon as the peripheral gripping arms 102 have engaged the roll to hold the same during its next operation of movement in the cycle of movement thereof, the stud shanks 81 are withdrawn to release the heads 82 thereof from engagement with the core of the roll. During the retraction of the stud heads, crimping means begins to function for crimping the projecting ends of the wrapper into engagement with the ends of the roll. Retraction of the stud heads is through a sufficient distance and with appropriate timing so as to get the stud heads out of the way of the crimped portion of the wrapper. This cycle of the operation is clearly indicated in Figures 3 and 38. The structural mechanism accomplishing the retraction of the studs and crimping of the paper is illustrated to some extent in said Figures 3 and 38 and is further illustrated in Figures 7, 39 and 54, and in the detail showings of Figures 42 to 50, inclusive.

Shift collar 84 and forked arm 87 heretofore described are utilized for retracting the stud shank at this stage of the operation. Rollers 90 ride upon the third cam section 93''' and by virtue of the slope of the cam toward the spider, the end of forked arm 87 having the cam-engaging rollers 90 is swung toward the spider and the opposite end of the arm is swung away from the spider thereby moving the shift collar 84 away from the spider and the stud shank and head 82 away from the roll. The said stud head 82 is shown thus retracted in both Figures 46 and 47.

On said stud shank between the spider and the

stud head is a crimper base plate 123. This base plate is of substantially circular configuration and has a central bore for receiving the stud shank therefrom. Said base plate is made adjustable toward and away from the roll, thereby adapting the mechanism to operation upon rolls of different lengths. The base plate is therefore slidable upon the shank for adjusting purposes, and the shank is rotatable in the base plate during this period of rotation for winding the wrapper on the roll, as heretofore described. In order to keep the base plate from rotating with the shank, we have shown two dowels 124 parallel to the stud shank and extending from the said base plate into the spider, with which they preferably have a sliding contact so as to move back and forth with the plate when adjusted, but because of engagement by the spider are prevented from revolving around the stud as an axis.

Near the periphery of the base plate and extending toward the roll parallel to the stud shank are a plurality of posts 125 each shown bifurcated next its end toward the roll and pivotally supporting upon hinge pin 126 a crimper arm 127. Each said crimper arm has one end thereof extending outwardly from the hinge pin and another end extending inwardly toward the stud shank, each arm thus comprising a first class lever. Upon the stud shank 81 is a sleeve 128. The end of this sleeve toward the roll has spaced peripheral flanges 129. These flanges have radial slots 130 therein sufficiently wide to admit the end portions of said crimper arms 127. On said ends of the arms are pintle 131 which project sufficiently so as not to be displaceable through said slots, but may ride in a radial direction with respect to the flanges and between said flanges. Consequently, said sleeve 128 and flange 129 may be slid upon stud shank 81 and thereby swing the said crimper arm 127, the swing of the pintles being accommodated by the permissible movement thereof between said flanges. When the sleeve is moved to its furthest amplitude toward the roll, the outer ends of the arms are thereby swung to retracted position outwardly away from the roll, as shown in Fig. 42. When the sleeve is slid in a direction away from the roll, the outer ends of said crimper arm swings inwardly toward the roll in position such as shown in Figs. 45, 46 and 47, at which time the projecting portion of the wrapper beyond the roll is engaged and crimped. The edge of the wrapper is thereby brought down to a crimped burr of paper as indicated in Fig. 47 such that the projecting edge of the burr will readily enter the hollow end of stud head 82 which is adjacent to the burr when formed. As soon as the burr is formed, the stud shank and stud head begin a return movement toward the roll by virtue of the appropriate slope of the end portion of cam track section 93'''.

In order that a more uniform grip may be obtained in presenting the overhanging portions of the wrapper for crimping or gathering, and in order that it can be picked up by the chuck noses for placing into the core, the outer ends or heads of each of the crimper arms 127 may be provided with suitable means. Such means preferably may be in the form of rods 127' suitably pivoted at one end of the crimper arm as at 127'' with the other or loose end thereof free to slide within an opening of the next crimper arm. With the said pivotal and slidable rods functioning the crimper arms will comb all of the wrappers toward a point where the loose ends of the wrappers will be gath-

ered by the chucks and thereby be placed into the cores of the rolls.

For operating said sleeve 129 and crimper arms 127 the end portion of said sleeve toward the spider is shown as having a peripheral groove 132. Operating in this groove are the ends of a forked arm 133, said arm projecting laterally away from the sleeve and pivoted at 134, to ears 135 projecting from one of the posts 125 in a direction radially outward from the stud shank. Beyond the point of pivoting of said forked arm 133, said arm provides a roller 136 which rides within an appropriate cam track 137 during the period of shifting of the sleeve through a complete cycle of its amplitude of movement. Such a cam track is shown at the top of the machine in Figs. 37, 38 and 39. It is of course essential where the track is segmental with respect to the whole cycle of revolution of the rotor that the track-engaging roller shall align with the track where it is to enter the track and also that the crimping arms assume a normal open or retracted position and retain such a position during all parts of the cycle where the same are not under control of the track cam. In this connection therefore, it will be observed in Figs. 42 and 43 that the sleeve operation arm 133 is pressed in a direction to slide the sleeve toward the roll by a spring 138 mounted on a rod 139, said rod being pivoted to the arm at one end and slidable through a lug 140 projecting from a rear part of one of the arm supporting posts 125. Sliding of the sleeve to a definite forward position is limited by engagement of stop pins 141 projecting laterally from the crimper arms 127 and engaging against the sides of posts 125 next the bifurcated end portions thereof when the outer ends of the arms are in their retracted or distended positions.

As indicated above, the stud shanks move inwardly toward the roll as soon as the wrapper is crimped, and the burr on the wrapper is formed. The stud head engages the burr and forces the same into the core of the wrapper, the operation being shown in progress in Fig. 48 and shown completed in Fig. 50. When the stud head is in its completely inserted position of Fig. 50, the controlling arm for the stud shank has swung its entire limit by virtue of its roller 90 having traveled to the end of the cam track section 93'. Thus, the wrapping is completed and the roll is entirely encompassed by the wrapper with the edges of the wrapper tucked into the core of the roll.

As a final operation, the stud heads are jerked out of the core, the peripheral gripper arms 100 are released from their gripping engagement with the roll, and the roll is deposited upon a discharge chute 142 upon which it preferably rolls by gravity and from which it is removed and packed with others for shipment.

Removal of the stud heads from the core, is, as indicated, obtained with a sudden movement by a rapid incline of the forward end of cam track section 93'. This sudden movement overcomes frictional engagement of the stud head with respect to the wrapper, without bringing the wrapper out of the core with the retraction of the stud heads. The said cam section 93' holds the stud heads retracted while the rotor continues its cycle and brings the stud shank back to the position toward the bottom of the machine where another roll is picked up and the cycle repeated.

Reference now will be had to section E of the machine, and more particularly to the part of that section illustrated in Figures 6, 9, 10 and 11

as enlargements of and showing details of the said section appearing at the left-hand end of Figure 1 and the right-hand end of Figures 2, 4 and 5. It will be remembered that section E attaches at its forward end to section D of the machine which is interposed between sections E and C. The physical location of the motor or other power driving means is, as shown in Fig. 1, situated in section C, and through various gears and the like, power is transmitted to section E and applied to a driving gear 150 shown at the upper left-hand corner of Fig. 6 next the said end of the said section. The shaft 151 on which said gear 150 is mounted, will, for convenience of identification, be referred to as the main driving shaft for section E. For the moment suffice it to say that said gear is fixed upon the shaft and is located on the outside of one of two standards or housings 152 which stand upright from the floor in parallel spaced relation at opposite sides of the machine, said shaft extending crosswise between housings and projecting at one end for mounting said gear. At the outside of said driving gear 150 is fixed a bevel gear 153 which in turn meshes with another bevel gear 154 fast on a transmission shaft 155 also at the outside of said housing and extending from the gear in a direction toward the feed end of the section to a mid-position of the upper part of said section. This shaft is journaled in suitable bearings 156 and at its other end has another bevel gear 157 which in turn is in mesh with a similar bevel gear 158 on the outer end of a secondary main driving shaft extending across the machine and journaled in the said housings. The several bevel gears 153, 154, 157 and 158 are all shown to be of the same size and consequently both the main driving shaft 151 and secondary driving shaft 159 are driven at the same rate of speed. Between the last mentioned bevel gear 158 on the end of secondary shaft 159 and the housing is mounted a spur gear 160 which is fixed with respect to the said bevel gear and shaft so as to rotate therewith. Diagonally below this spur gear and in mesh therewith is a smaller gear 161 fast upon a wrapper feeder shaft 162. This feeder shaft is accordingly somewhat nearer the feed end of the section than the secondary driving shaft and also at a lower level than said secondary driving shaft. Said feeder shaft extends parallel to the main driving shaft and secondary shaft and is journaled in the said housings, with one end projecting for receiving the said smaller gear 161 at that side of the machine.

Between the said housings and journaled on said feeder shaft are two rocker arms 163, one arm being situated near one housing and parallel thereto and the other arm near the other housing and parallel thereto and to each other and both projecting from the feeder shaft in a direction toward the wrapper feeding end of the machine. The said projecting ends of rocker arms 163 support driven shaft 164 which may be referred to as the secondary wrapper feeder shaft. The first mentioned or primary wrapper feeder shaft 162 and the secondary wrapper feeder shaft 164 are both revolved in the same direction and at the same speed by suitable means. The actual means here shown for obtaining the simultaneous equal rotation of these two shafts constitutes spur gears 165 of equal size and pitch on both shafts and both in mesh with an idler gear 166 interposed therebetween and mounted on one of said rocker arms 163. Both said wrapper feeder shafts 162 and 164 have friction wheels 167 at

intervals thereon between the said rocker arms 163. Said wrapper feeder shafts also are provided with pairs of aligned pulleys 168 around each pair of which is a continuous belt 169. The function of the friction wheels is to feed the wrapper 94 forwardly toward the adjacent section D or pasting section of the machine, by making physical contact with the surface of the said wrapper. The belts 169 have their lower reaches traveling in the direction of feed of the wrapper and serve to prevent the wrapper from curling upward between the shafts and to necessitate the forward edge of the wrapper continuing from the friction wheels on one shaft forward to the friction wheels of the next shaft.

The secondary wrapper feeder shaft 164 and its friction wheels 167 are situated over the forward margin of a stack of wrappers, and it is a purpose of the present machine to interpose a gap between the successively fed wrappers. It is for this purpose, therefore, that the secondary wrapper feeder shaft is mounted on said rocker arm 163 thereby enabling the said secondary shaft to be lifted before the trailing end of a wrapper has passed from under said shaft and its wheels. The mechanism is timed so that when the desired gap exists between a wrapper already fed and the next wrapper on the stack, said secondary wrapper feeder shaft is lowered and its wheels brought into contact with the next wrapper on the shaft so as to begin to feed the same to follow the preceding one with an interval between them. As here shown, each rocker arm is provided with an extension 171 projecting normal to wrapper feeder shaft 162 at the side thereof away from the secondary wrapper feeder shaft, that is to say forwardly of the machine. The forward end of each of these extensions 171 makes contact with a cam 172 (see Fig. 11) situated above the said extension and fast upon secondary driving shaft 159. The shape of the cam is such that the extension is depressed and the rocker arms swung upwardly for the desired length of time and at the intervals necessary for accomplishing the operation just described for feeding the wrappers intermittently. Suitable springs 173 are provided for actuating the extensions 171 and rocker arms 163 to normally maintain contact of the extension with the cam and contact of the friction wheels of the secondary wrapper feeder shaft with the wrappers except during the interval of positive swinging of the extension and arms by the cams. As here shown, said springs are situated on rods 174 pivoted to said extensions and sliding through appropriate lugs on the housing.

In section E it is desirable in connection with the feed of wrappers from the stack of wrappers, to prevent more than the top wrapper of the stack to be fed or removed from the stack at one time. For convenience such means will be referred to as the wrapper detainer. As best shown at the right end of Figures 6, 9 and 11 and in the detail showing of Figures 12 and 13, a spur mechanism is provided as part of the detainer. The specific constructions illustrated utilize a fixed tie rod 175 extending across the machine at the extreme upper right end thereof as a means of support. Two detainers are shown mounted on this tie rod, although any number of detainers may be employed, and description of one will suffice for an understanding of both.

Each said detainer comprises a sleeve 176 mounted on the tie rod adjustable to desired position lengthwise of the tie rod and adjusted posi-

tion rotatively on the said tie rod, it being understood that after the sleeve is adjusted for any particular stack of wrappers, the said sleeve maintains a fixed relationship upon the said tie rod, neither sliding nor rotating while the machine is operating. From the sleeve, projecting forwardly substantially over the stack of wrappers is an upper arm 177 and projecting downwardly rearward with respect to the sleeve and also fixed with respect thereto is a rear arm 178, the lower end of which provides a pivotal support for a swinging bracket 179 having one portion thereof extending forwardly below the tie rod and upper arm 177 and having a rear or mounting portion extending laterally substantially parallel to the tie rod. It is to this lateral portion of the swinging bracket that the bracket is pivotally supported next the lower end of rear arm 178. At the forward ends of both the upper arm 177 and swinging bracket 179 is interposed a spring 180 held in position by a rod 181 pivoted to the said bracket and slidable upwardly through the forward end of said upper arm. Since, in use, said upper arm maintains a fixed position, the spring tends to depress the forward end of swinging bracket 179 upon its pivotal support 182. Extending forwardly through the lateral mounting portion of swinging bracket 179 is a rod 183 which projects inwardly over the stack of wrappers. This rod 183 is substantially parallel to the forwardly extending portion of bracket 179 and swings up and down with the said bracket. On said rod is a rider 184 from the underside of which projects a spur 185. Preferably the spur is in the nature of a removable knife pointed at its lower end so the point will dig into the wrappers in the stack and the rear edge of the knife will act from its point of insertion to the rear edge of the wrapper as the wrapper is withdrawn. Since the spur digs into several wrappers at one time and since the removing impetus for the wrapper is applied only to the upper wrapper of the stack, the upper wrapper is the only one which will be slit and the spur will retain the next lower wrapper from sliding forwardly. The adjustment available both between the rider 184 and its supporting rod 183 and between the said rod 183 and its mounting in the lateral projecting portion of swinging bracket 179, enables the spur to be located closely adjacent the rear edge of the stack of wrappers regardless of the particular size of wrapper being utilized in the machine for any one job. Likewise since the sleeves 176 of the detainers are adjustable longitudinally of the tie rod, the spurs can be adjusted with respect to the width of the wrappers so as to exert an even detaining tension near opposite side edges of the wrappers.

The stack of wrappers is supported upon an elevating table 186 on the top of which are adjustable side cleats 187 for engaging the side edges of the stack of wrappers for whatever size of wrappers may be utilized at any particular time or for any particular job. It is a purpose of the elevating table to maintain the uppermost wrapper of the stack substantially at a constant lever so that it will be at the proper elevation for removal from the stack by the friction wheels heretofore described regardless of how many wrappers still remain in the stack.

Mechanism is accordingly provided for automatically elevating the table as wrappers are withdrawn therefrom. In Figures 4 and 15 said table is illustrated as having two vertical toothed racks 188 depending from the middle of opposite side portions, each said rack passing through a

fixed vertical guide-way 189 and having a spur gear 190 in mesh with the teeth of the rack in proper relationship whereby rotation of the gear will raise or lower the rack an amount corresponding to such rotation. Said spur gears, as indicated in Figures 4 and 15 are mounted upon a common shaft 191 extending across the machine below the table and projecting beyond one of the housings 152. On this outer end of the shaft is a sprocket wheel 192 and since both the spur gear and the sprocket gear are fast upon the shaft, rotation of the sprocket will rotate the shaft and spur gear and will obtain a vertical movement of the table. From the said sprocket wheel, extending continuously, is a sprocket chain 193 to an upper sprocket wheel 194 rotatably mounted upon a stub shaft 195 at an upper part of the machine preferably at a lever above the friction wheels by which the wrappers are fed. In this connection, attention is directed to Figures 14, 15 and 15A particularly, although the general organization of parts now to be described also appears in smaller scale in such Figures as 4, 5, 6, 10 and 11. At the outside of this upper sprocket wheel 194 is a crank 196 by which the sprocket wheels may be rotated and the table raised or lowered by hand whenever necessary. The crank is ordinarily used to lower the table whenever a new supply of wrappers is to be placed upon the table, and then to bring the upper most wrapper into its proper relationship to the friction wheels and detainers. Otherwise, raising of the table is effected during operation automatically.

On said stub shaft 195 carrying upper sprocket wheel 194, between said sprocket wheel and the housing 152, in the order now mentioned, are carried a pawl detaining arm 197, a ratchet wheel 198, a pawl operating arm 199, pressure applying arm 200 and a cam engaging arm 201. Said stub shaft 195 is immovably carried by the housing, and, as shown in Figure 15A, carries two sleeves 202 and 203 situated end to end thereon. The sleeve 203 next the housing is free to oscillate on the stub shaft and sleeve 202 next the outer end of the shaft is adapted to rotate thereon. Also, said crank 196, upper sprocket wheel 194 and ratchet wheel 198 are fixed on the outer sleeve 202 so as to rotate therewith in unison, but the pawl detaining arm 197 interposed between the upper sprocket wheel 194 and ratchet wheel 198 is rotatably mounted with respect to the sleeve so the sleeve may rotate without causing said arm 197 to rotate.

Said pawl detaining arm 197 is under control of a feeler mechanism operated by the elevation of the top wrapper on the stack of wrappers. As here shown, a link 204 is pivoted to said arm 197 and extends horizontally toward the right end of the machine (as viewed in Figs. 9, 11 and 14) and has adjustably pivoted thereto the upper end of a lever 205, the lower end of which is attached to a rocker bar 206 next one end thereof, said rocker bar extending across the machine immediately above the stack of wrappers. The pivotal connection of said link 204 and lever 205 may be accomplished with an adjusting slot 207 shown in Fig. 14 in the said link, movement of the pivot in the slot taking place only while adjustment is being effected and only pivotal movement occurring between the said link and lever during operation of the machine. At a suitable position on the rocker bar 206 is fixed a horizontal feeler lever 208 conveniently equipped with a roller 209 at its end. This

roller engages the upper wrapper of the stack and accordingly introduces no interference with the withdrawal of the wrappers. Normal position of the several parts just described is indicated in full lines. When one or more wrappers are withdrawn to some such level as indicated by the dot and dash lines of Figure 14, roller 209 sinks by gravity or otherwise to the new position, thereby swinging rocker bar 206, lever 205, link 204 and pawl detaining arm 197 all as indicated by dot and dash lines. The pawl detaining arm has a pawl detaining shelf 210 at its upper end projecting over the ratchet teeth for a short segment of ratchet wheel 198. The pawl operating arm 199 carries a pawl 211 for engagement with ratchet wheel 198. The pawl shelf 210 is substantially beneath the said pawl so that when the pawl detaining arm and shelf are swung forwardly in their normal position, the pawl will ride upon the said shelf, which is at that time interposed between the pawl and ratchet wheel, and prevents feeding contact of the pawl with respect to the ratchet wheel for the entire stroke of said pawl. However, when the pawl detaining arm and shelf are swung to the left (as viewed in Fig. 14), the shelf 210 will expose a corresponding number of ratchet teeth for feeding actuation of the pawl, and as a result, as the pawl moves through its stroke in a feeding direction, the ratchet wheel is intermittently rotated with a step by step motion until the pawl is again out of contact from the ratchet by the shelf interposing itself between the pawl and ratchet teeth. Rotation of the ratchet wheel under impetus of the pawl transmits through the sprocket wheels the aforementioned step by step motion to the elevating gears and racks on the table, thereby elevating the stack of wrappers so the top wrapper is at normal position. This elevation of the stack of wrappers again returns the pawl detaining shelf to its position where it is interposed between the ratchet and the pawl and stops further elevation of the stack of wrappers until the cycle of operations is again set in motion by the removal of wrappers from the stack. Retractive rotations of the ratchet wheel is prevented by a detaining pawl 212 which remains in constant engagement with the ratchet wheel. This pawl is shown as carried at the end of a fixed bracket 213. We have shown this bracket of goose-neck shape and as supported from the inner end of stub shaft 195, although other support and shape might be arranged. When it is desired to lower the table by use of crank 196, both said pawls 211 and 212 are thrown out of engagement with the ratchet wheel thereby enabling the ratchet wheel to be revolved backwards until the new stack of wrappers is inserted and brought to its proper level.

On the inner sleeve 203 carried by stub shaft 195 are secured the pawl operating arm 199, pressure applying arm 200 and cam engaging arm 201 so that all three of these arms will oscillate simultaneously. Cam engaging arm 201 extends upwardly and forwardly and makes riding contact with the periphery of an eccentric or other cam 214, rotation of which causes the cam engaging arm to oscillate back and forth. Said cam engaging arm is held in contact with the operating periphery of the cam by spring tension applied through the said pressure applying arm. According to the present showing, said pressure applying arm has a rod 215 pivoted at its lower end, said rod extending horizon-

tally through a lug on the housing. An adjustable dog 216 is secured on the rod and a spring 217 is interposed between said lug on the housing and dog on the rod for exerting an operating pressure tending to swing the arm and keeping the cam-engaging arm operatively against the cam. The stroke of the pawl operating arm is thus determined by the cam and spring and the said cam-engaging arm accordingly oscillates continuously back and forth. Said cam is driven by a gear 218 fixed with respect thereto, said gear being in mesh with a smaller gear 219 shown in Figs. 6 and 14 on the aforementioned secondary drive shaft 159 and located between spur gear 160 thereon and the housing.

The wrappers from the stack, being fed forward intermittently therefrom by the mechanism above described, are advanced upon a delivery way forming part of the section E being described and there positioned ready to advance to the adhesive applying or passing section D. The delivery way portion of said section E will now be described, particular reference being had to Figures 6, 9, 10, 11, 16 and 17. Preferably the way slopes somewhat forwardly downward to assist in the movement of the wrappers thereon.

As shown, the delivery way for the wrappers may comprise a plurality of parallel slats 220 extending forwardly in the direction of movement of the wrappers substantially from beneath the forward friction wheels 167 on wrapper feeder shaft 162 to the wrapper receiving means of the adhesive applying section. These slats 220 are carried upon the top faces of cross supports 221 secured at their ends to the housings. Situated between some of the slats are upper reaches of continuous belts or conveyors 222 which move in the forward direction of feed of the wrappers for advancing the wrappers toward the adhesive section along the delivery way. These belts or conveyors 222 pass around suitable pulleys 223, one set of which are upon a shaft 224 beneath and parallel to wrapper feeder shaft 162, and the other of which, 225, is at the forward end of the delivery way next adhesive applying or passing section D and under main drive shaft 151. Either or both of shafts 224 and 225 may be power driven by actuating said belts or conveyors 222, and in Figure 6 it will be observed a gear 226 on the forward conveyor shaft 225 drives the same by meshing with driving gear 150. Furthermore, a roller-type belt-tightener 227 may be located below the way in contact with the lower reach of each conveyor belt, so as to keep the upper reach at proper elevation throughout its length to contact and feed the wrapper forwardly down the way.

The wrappers are guided at their side edges down the way by side rails 228 conveniently carried above the way by transverse tie-rods 229. Preferably the said side rails are adjustable laterally of themselves and longitudinally of the tie-rods for regulating the rails for different widths or feeding location of the wrappers. It is desirable to knock the wrapper at one side edge to insure its precise positioning when it arrives at its forward position on the way. As one means of accomplishing this function, one side rail is slideable upon the tie rods and held in adjusted position upon a movable rod 230 parallel to and substantially midway between the tie rods. This movable rod 230 has a longitudinal movement imparted to it which imparts a like lateral movement to the rail attached to it. The movement of said rod is shown accomplished by supporting

the rod at its ends upon a rider 231 and actuating the rider through engagement of a pin 233 thereon by a forked lever 234 the other end of which is periodically impelled by a protuberance 235 on a rotating member 236 fast upon shaft 151. (See Figures 6 and 9.)

Situated upon and rotated by means of driving shaft 151, are a plurality of friction wrapper-engaging feed wheels 237 having substantially the pitch diameter of driving gear 150 and overlying corresponding pulleys 223 on the forward conveyor shaft 225, these pulleys having substantially the pitch diameter of gear 226 by which they are driven from gear 150. The said friction feed wheels 237 have a segmental portion inset as at 238, so that for such segment the said friction feed wheels will be out of contact from the wrapper and applying no impelling feeding force thereto. The feeding mechanism is timed so as to bring this inset segment portion 238 immediately above the forward end of a wrapper to be fed at the time the wrapper arrives at the forward end of the way. The friction wheels accordingly will not exert an impelling force upon the wrapper at the moment of arrival of the wrapper thereunder. During this interval the wrapper is brought to a standstill so that the feeding of the wrapper to the next section D of the machine will be precisely timed and with the forward edge always located at a precise position for beginning the next advancing motion.

In order to precisely position the forward edge of the wrapper a plurality of aligned stops 239 are located substantially in a plane normal to the common tangents of friction wheels 237 underlying pulleys 223. Said stops 239 are movable and operated in timed relationship as the inset portion 238 of feed wheels 237 so as to be in the path of movement of the wrapper only during the period while said inset portion is passing said stops. The moment the outer friction surfaces of the feed wheels engage the wrapper, the stops are depressed below the way and out of detaining contact with the forward edge of the wrapper. Suitable mechanism may be utilized for accomplishing this operation. As here shown, the stops comprise upturned lips at the forward ends of elongated strips 240, the rear ends of the strips being bent downwardly to provide tabs 241 through which extend adjusting screws 242. The elongated strips 240 are slidably held in an appropriately grooved portion of a rocker block 243 and the said adjusting screws also engage within the respective rocker blocks. By the mechanism just described, the precise position for the said stops 239 is accomplished. The several rocker blocks are secured upon a transverse rocker shaft 244 extending crosswise of the machine between the reaches of the conveyor belt. At one end of the rocker shaft is an upwardly extending arm 245 which makes contact with a cam 246 on drive shaft 151. This contact of cam arm 245 and cam 246 is maintained by suitable spring pressure. As shown, a horizontally extending arm 247 is also provided on said rocker shaft 244, the outer end of the arm having a rod 248 pivoted thereto, said rod slidably passing through a lug on the housing. A spring 249 is interposed between said lug and a dog on the rod for exerting the desired spring pressure. The function of the cam and spring has been explained above for introducing stops 239 in the path of movement of the wrapper during the interval of non-contact of the friction wheel and wrapper, but functioning to lower the

stop immediately the friction surface of feed wheel 231 engages the wrapper to advance the same into the adhesive applying or pasting section D of the machine.

As was indicated in an earlier part of this specification, the invention contemplates not only the supply of wrappers from a stack of wrappers as last described, but contemplates feeding wrappers from a strip or web, as in section F, the web to be cut appropriately between the similarly printed portions thereof to thereby introduce the severed individual wrappers successively to the adhesive or pasting section D. The web feeding, cutting and timing mechanism is more particularly illustrated in Figures 25 to 36 inclusive, and the same will now be described. It will be noted, however, that as a matter of convenience, the web is introduced from a source of supply which is a rolled web 250 shown at the left-hand end of Figure 1 and the right-hand end of Figures 2 and 4. The rolled web is shown supported upon a mandrel 251 the ends of which are removably supported in sockets at the upper ends of stanchions 252 in turn carried upon the housings 152 of section E.

Section F of the machine comprises side housings or standards 253 which extend upwardly from and supported by section D of the machine. These standards are shown sloping rearwardly upward toward the wrapper entry end of the machine and provide rearwardly extending beams 254, the rearmost end of each of which is shown bent downward and the two beams carrying an idler roller 255 (Fig. 4) extending crosswise of the machine with its ends journaled in the said rear ends of the beam. Also extending crosswise of the machine and journaled at its ends in the two beams approximately midway of the length of the said beams is another idler roller 256 parallel to and at a higher elevation than the first said roller. Next the front upper corner of the beams and standards is another roller 257 parallel to the said idler rollers. The construction shown, is such that the unrolled feeding portion of the web 258 leaves the rolled web 250 at the upper forward part thereof, passes under the first idler roller 255 and then upwardly over the second or middle idler roller 256 and then horizontally forward to the third mentioned roller 257 where it is deflected downward toward the bottom of section F to feed into the adhesive applying or pasting section D. The said third roller 257 at the forward upper part of the standards cooperates with a feeding roller 259 juxtaposed thereto immediately forward thereof so that the web 258 passes downwardly between the two said rollers. The said feed roller 259 is closely positioned against the juxtaposed roller 257 in order to obtain frictional feeding contact with the web. Certain mechanism, to be subsequently described, is associated with this feeding roller 259 for timing the feeding of the web in conjunction with the printed matter thereon in its relation to the cutting mechanism next to be described.

As the unrolled web passes downwardly from the roller 257 and juxtaposed feeding roller 259, it comes into surface engagement with a cutting roller 260 situated a spaced distance below the said feeding roller, parallel thereto, and journaled in the said standards 253. In front of this cutting roller and in front of the web is a rotating cutter shaft 261. Upon this shaft inside the housings but spaced apart a distance greater than

the width of the web, are cutter arms 262. These arms carry next their outer ends a suitable bar which is parallel to the shaft and constitutes a blade backing 263. On this blade backing is mounted longitudinally thereof a blade 264, the longitudinal outer edge of which projects beyond the backing and projects far enough from cutter shaft 261 so as to enter a cooperating cutting slot 265 in the said cutting roller 260 each time the blade makes a complete revolution. It is by virtue of the said outer edge of the blade entering said cutting slot that the web is severed entirely across the web thereby releasing a single wrapper from the web to be fed into the adhesive section for further manipulation and use. The cutter arms 262 and blade backing and blade are suitably counter-balanced by a diametrically oppositely situated weight 266 here shown as a bar extending between portions of the said arms 20 that project from the cutter shaft at the opposite side thereof from the blade backing and blade.

In order to feed the unrolled wrapper forwardly past the cutting roller after the preceding wrapper has been severed from the web, I have shown a plurality of arcuate horns 267 carried at the following side of the blade backing from the blade, the said horns having the arcuate outer surfaces thereof toward the cutting roller when in their position as shown in Fig. 29, situated to engage the forward face of the web immediately above the transverse cut and press the web against the cutting roller. Both the cutting roller and the said horns are moving with equal surface speed and the lower edge of the web will accordingly be actuated downwardly by the frictional contact of the arcuate faces of the horns. As shown in Fig. 25, several horns 267 may be employed at spaced intervals along the said blade backing bar so as to give the desired frictional contact with the web and obtain even pulling for the web so the same will feed straight and also to accommodate the machine to use of various widths of webs. Below the cutting roller 260 on a shaft 268 parallel thereto are a plurality of pulleys 269 on which ride conveyor belts 270 which extend to similar pulleys 271 on a bottom shaft 272 and around the pairs of pulleys for actuating the cut wrapper below the cutting roller in its further progress to the adhesive section. Between the successive pulleys and conveyor belts are slats or ways 273, and above the cutting roller are corresponding slats or ways 274, aligned with the ones between the conveyors so that the downwardly progressing web and cut wrappers are in a common plane sloping forwardly downward.

It will further be observed that the said slats or ways 273, 274 are behind the cut wrappers and web and extend substantially to the cutting roller. The upper series of pulleys 269 for the conveyor belts are arranged as close as possible to the cutting roller so the lower feeding edge of the web will come into engagement with the conveyor belts during the period that the arcuate friction surfaces of the horns are still feeding the web downwardly. After the horns disengage from the web, the web is still being fed by the upper rollers 258 and 259, and by the physical contact of the web under the influence of its own weight against the cutting roller 260 and conveyor belts 270.

In front of the web and conveyor belts 270 are situated forward conveyor belts 275 which pass

over upper pulleys 276 spaced forwardly from the web but which slope downwardly rearward so as to ultimately engage the forward face of the cut wrapper and positively feed it in its further progress to the adhesive section. It will accordingly be observed that somewhat below the upper series of pulleys 269 and 276 between the reaches of the respective conveyors are situated parallel advancing rollers 277, 278. The wrapper engaging reaches of the two conveyors engage the wrapper on opposite faces and those reaches and the wrapper pass between the said advancing rollers which are closely enough situated to insure frictional engagement between the said reaches and the wrapper for advancing purposes. From the said advancing rollers to the lower part of the machine, the said reaches remain in contact with the faces of the wrapper and thus both guide and feed the same downwardly. The forward conveyor belts pass around a large bottom roller 279, and this roller with the conveyor belts and supplemental guiding means 280 deflects the wrapper from its downwardly forward feeding direction into a horizontal forward feeding movement in the adhesive section. The said guiding means 280 is a fixed part suitably shaped to engage the rear side of the wrapper where it leaves the bottom and rear pulleys 271 for curling the forwardly feeding lower edge of the wrapper around the rear and underside of the large bottom roller 279. This same supplemental guiding means 280 also has a rearwardly directed chute-like portion 280A for receiving the forwardly feeding edge of the individual wrappers from the stack of wrappers heretofore described as fed from label feeding section E. It will accordingly be understood that where the wrappers are fed from the stack of wrappers or where fed and cut off from the web supply, they arrive at the adhesive applying or pasting section to feed horizontally and forwardly under the large bottom roller 279. The wrappers are held in feeding contact with this said roller 279 by a horizontally disposed conveyor and pulleys which will be hereinafter described when dealing more specifically with the adhesive applying section.

All of the several rollers and pulleys mentioned in the preceding description of section F of the machine are carried upon suitable shafts, and except for one instance, all of said shafts are journaled directly in the stanchions 252, 252. The one instance where this is not the fact, is in connection with the support of the upper forward pulleys 276 for the forward conveyor belts 275. Those pulleys are mounted upon a shaft 281 (see Figs. 25, 26 and 27) the ends of which are carried by upwardly rearwardly directed arms 282, the forward ends of which are adjustably gripped upon fixed rods 283 carried one by one housing and another by the other housing. One of these rods at the side of the machine having the driving train of gears, projects through the housing and constitutes both an axle for an idler gear (hereinafter more definitely mentioned) and said rod supporting below the idler gear other mechanism also to be described below. For purposes of this description, attention is called to Fig. 25 particularly where the train of gearing for actuating the several rollers and other mechanism is shown at the left side of the figure.

Power for driving the several rollers is applied from the motor or other source of power, hereinafter located, through an appropriate train of

gearing forming part of the adhesive applying or pasting section and functioning to actuate a wide main driving gear 284, for the section F now being described which is mounted upon and fast with respect to the shaft carrying the large bottom roller 279. This large driving gear has a pitch diameter equal to the diameter of said large bottom roller 279. Situated somewhat upwardly and to the rear of this driving gear 284 is an idler gear 285. It may be stated at this time that this idler gear 285 is in mesh with the main driving gear 150 of section D (see Fig. 1). It is also in mesh with two other gears, one of which, 286 is another idler gear situated forwardly and upwardly therefrom and of equal pitch diameter. The other of the two gears which is in mesh with said idler gear 285 is upwardly and to the rear thereof and comprises a clutch driving gear 287 which will be shortly referred to. Above idler gear 286 is a third idler gear in the series, identified as idler gear 288, and this gear is rotatable and situated upon the aforementioned projecting rod 283 which constitutes its axle. Above this third idler gear 288 is a driven gear 289 which is secured to and rotates with aforementioned rotating cutter shaft 261. It will accordingly be seen that this train of gearing gives a constant rotation of the rotating cutter shaft 261. Spaced outwardly from the driven gear 289 and both on and fast with respect to the cutter shaft is a smaller gear 290. This said smaller gear 290 is in mesh with an idler gear 291 situated somewhat forwardly and upwardly thereof and carried by a boss 292 or other suitable means projecting outwardly from the side of a pivoted hanger arm 293. Said idler 291 carried from hanger arm 293 is in mesh with a wide gear 294 which constitutes the main driving gear of a differential mechanism. This main differential driving gear 294 is rotatably mounted upon a stub shaft 295 fixed with respect to and projecting outwardly from the stanchion. Hanger arm 293 is pivotally hung next the stanchion upon this stub shaft 295 so that its center of oscillation is coincident with the axis of said shaft and main differential driving gear. Accordingly, the main differential driving gear and the said idler 291 always remain in mesh irrespective of any swinging of the hanger arm. The outer end of the hanger arm is provided with a head 296 in which is an arcuate slot 297, the center of curvature of which is also coincident with the axis of said stub shaft. A suitable bolt or other means 298 passing through said slot into the stanchion enables the hanger arm to be situated at the desired adjusted position and retained in such position. In normal operation of the machine, the hanger arm is adjusted to its downward position so the said idler gear 291 is in mesh with the smaller gear 290. However, the hanger can be swung upwardly and release the meshing engagement of gears 290 and 291 and a different gear 290 substituted, if so desired, for changing the gear ratio. Furthermore, the release of the meshing of these gears may also be utilized for enabling the web to be introduced to the cutter with the gears above the cutter operating gear to be then independently rotated by hand for properly situating the web ready to begin operation.

It is a purpose of the mechanism now being described to enable the same to automatically advance the web, where it is necessary, in excess of its normal downward movement to the cutter in order to secure accuracy of cutting notwithstanding

ing a tendency otherwise for the web to lag and get out of registration. A differential drive is accordingly applied to the upper feeding rollers 257 and 259 in actuation thereof from the constant rotation of the cutter shaft. As here shown, the differential mechanism comprises the heretofore mentioned main differential driving gear 294 on stub shaft 295 in combination with a similar wide driven differential gear 299 rotatably mounted on the same shaft inwardly of the first said gear and between it and the stanchion. Between the two said differential gears 294 and 299 is rotatably mounted on the same stub shaft, a ratchet wheel 300. This ratchet wheel, at an appropriate distance radially outward from the axis thereof, provides brackets 301 on opposite sides thereof and each carry therebetween differential pinions 302, both of which project longitudinally of themselves through the ratchet wheel through a suitable opening provided therein. One of these differential pinions 302 is in mesh with the driving differential gear 294 and the other of said differential pinions 302 is in mesh with the other or driven differential gear 299, and both the said differential pinions overlap at their adjacent ends and are in mesh with each other. Under ordinary conditions, with the ratchet wheel standing still, the two differential pinions transmit the rotary motion of the driving differential gear 294 to the driven differential gear 299 so that those differential gears are rotating at the same speed but in opposite directions. The driven differential gear 299 is in mesh with a gear 303 on the axle of web feeding roller 259, and accordingly applies a positive driving force to that roller. In event the web is lagging so the proper line of cutting does not register with the blade where the cut is actually made, ratchet wheel 300 is given an actuation in a direction opposed to the rotation of the driving differential gear but in the same direction as the rotation of the driven differential gear. This accordingly varies the relationship of the differential pinions of the differential gears, and results in the driven differential gear being advanced peripherally a greater amount during the interval than mere normal rotation of the differential pinions would have effected.

In order to automatically operate the ratchet wheel 300, I have shown the ratchet wheel provided with an advancing pawl 304 and with a retaining pawl 305. The retaining pawl is shown mounted upon a suitably positioned and projecting pawl support 306 and is held in engagement with the ratchets of the ratchet wheel by a suitable spring 307. The advancing pawl 304 is pivoted at the upper end of a lever 308, said lever extending downwardly and being pivoted upon the same stub shaft 295 with the differential gears and ratchet wheel. The lower end of this lever projects diagonally downwardly and rearwardly and has pivotally secured thereto an operating arm 309. This arm 309 slopes downwardly forward and is forked to ride upon the cutter shaft 261. Next said arm is an eccentric 310 fast upon the cutter shaft and having engagement at its periphery with an anti-friction wheel 311 carried at a mid part of said arm 309. A spring 312 engaging a suitable part of lever 308 draws the anti-friction wheel into constant engagement with the periphery of the eccentric. Accordingly, as the cutter shaft rotates, the eccentric rotates and causes lever 308 to swing back and forth, carrying pawl 304 with

it. Between the advancing pawl 304 and the ratchet teeth is situated a pawl detaining shelf 313. This shelf keeps the pawl from engaging the ratchets of the ratchet wheel while the web is feeding so the cutter and desired line of cutting are registered. When the web gets out of registration, the shelf is automatically retracted and the pawl is then allowed to engage the ratchet wheel and operate the same until registration of the web is again occurring. The automatic means for operating this pawl detaining shelf will be next described.

The above described pawl detaining shelf 313 is carried at the lower end of a long arm 314 of a bell crank lever, the mid part of said lever being pivoted at 315 to a suitable bracket 316 extending upwardly and outwardly from the housing. The short arm 317 of the bell crank lever extends horizontally from the pivot and is connected pivotally at its outer end with a link 318 the upper end of which is pivotally connected to the end of an armature 319 in turn pivoted at 320 with respect to said bracket 316. Above the armature is an electromagnetic means either in a form of a simple magnet or solenoid 321 cooperating with the armature 319 for lifting the armature and swinging the bell crank lever under the influence of electrical impulses applied thereto by means yet to be described. A spring 322 (Fig. 29) augments gravity in keeping the armature in its retracted or downward position away from the solenoid except as a magnetic influence may raise the armature. From an inspection of Figure 29 particularly, it will be observed that when the armature is in its normal or rest position, the bell crank lever is swung to interpose shelf 313 between the pawl and ratchet wheel, but when, as indicated in said figure, the magnetic means is being actuated by an electric current, the bell crank lever is retracted so as to enable the pawl to engage the ratchet wheel. As soon as the current ceases, the magnetic influence ceases, and the bell crank lever will swing back to its normal position with the shelf keeping the pawl out of contact with the ratchet wheel.

The electric circuit for creating the magnetic field in the solenoid is under control of several instrumentalities. As shown in Figures 29, 30 and 32, a pair of commutator rings 323, 323 are secured upon the cutter shaft 261 and shown located on said shaft between the eccentric and the outer smaller gear 290. These commutator rings each have short arcuate portions which are electrically connected by any suitable means, but which are insulated from the completing portion of each of said rings and from the supporting shaft. Said completing portions of said rings are insulated from all supporting parts and are therefore "dead" portions electrically. Suitable brushes or other contact members 324 are in contact, one with each of said rings and are otherwise electrically insulated from each other. As here shown, said brushes are mounted in a supporting arm 325 clamped to the fixed axle on which idler gear 288 rotates. The said brushes and commutator ring sections accordingly constitute a switch and are arranged in proper relationship to the cutter so as to complete the electric circuit (if otherwise complete) only at a time while the cutter is in proximity to its cutting roller 260. At other times, the brushes are merely riding upon the "dead" portions of the commutators.

When the web is printed with the label or other

decoration, it is also printed with dark spots or other markings 326 (see Figs. 35 and 36) preferably at the precise position where it is desired to cut the wrapper therefrom. A scanner 327 is provided at appropriate position over the advancing web which will be affected by the presence of the dark spot 326 passing beneath the same. This scanner 327 is shown in Figure 26 as supported by a suitable bracket 328 which positions the said scanner above the horizontally moving portion of the web where passing from idler roller 256 to the upper corner roller 257. The position of the scanner is such that when the cutter is properly severing a wrapper on the line where the cut is desired, the dark spot of the web under the scanner will be registering to impress a vision of the said dark spot upon the scanner. Under this condition, however, the "live" portion of the commutator rings have not yet made contact with the brushes but the brushes are in contact with the "dead" portion of the commutator ring and the electric circuit is thus kept open by the relation of the commutator rings and brushes. However, if the web is lagging and the cut is made in advance of a mark, the mark under the scanner arrives under view of the scanner after the cut has actually been made and by that time the "live" portion of the commutator rings are in contact with the brushes and thus the electric circuit through the commutator rings is closed. It is then desirable to have the scanner influence the circuit or otherwise obtain a current flow through the solenoid and thereby advance the web under influence of the ratchet wheel operating and bringing the web back into proper registration with the cutter. The scanner 327 is accordingly employed not only in association with the circuit closing of the commutators and brushes and in association with the solenoid, but in proper electrical connection with a device commercially known as a "photo-troller" or its equivalent. The photo-troller is primarily and essentially a relay which functions to admit current to the solenoid when there is a simultaneous closing of the circuit of the commutators and brushes and of a circuit through the scanner.

While the construction of the photo-troller is not per se part of the present invention, yet, for purposes of making the operativeness of the combination more readily apparent, the fundamentals of the photo-troller have been illustrated in Figure 34. It should also be noted that the particular type of scanner is selected to cooperate with the photo-troller and that this also is illustrated with its essential elements in Fig. 34.

Briefly, therefore, it may be stated that the scanner comprises an "electric eye" or light responsive device 329 which is more conductive to an electric current when light is directed upon its sensitive surface than when a shadow crosses the sensitive surface. An electric lamp 330 the beam of which is directed by lenses 331 is provided in association with the electric eye. The light beam is directed against the underlying web so as to reflect from the web to the sensitive surface of the light responsive device. The dark spot on the web crosses under the beam and therefore with each passing of a dark spot a shadow is cast upon the light responsive device. At that moment, there will be a lessening of the current flow due to the dark spot. The relay of the photo-troller is arranged to utilize this lessening or even elimination of current flow due to the dark spot, to set up an amplified current

flow in a series circuit through the commutator "live" spots and brushes (if in contact) and the solenoid.

Referring now to the essential elements of the photo-troller, it will be observed that an exterior supply of A. C. current is introduced for actuating the primary 332 of a transformer. One secondary 333 from the transformer sets up the current in leads 334 to the electric lamp 330 of the scanner and thus obtains a constant illumination thereof. Another secondary 335 supplies a constant current to a heater filament 336 of a dual-grid-electron tube 337. Another secondary 338 provides a constant current supply to a filament-cathode 339 of a triode-electron-grid-glow-tube 340. The plate 341 of this last mentioned triode tube 340 is connected by a lead 342 to one of the brushes 324 and from the other brush 324 is a lead 343 to the solenoid, which for convenience of connection may pass through the photo-troller. From the other end of the solenoid a further lead 344 connects with another secondary 345 in the photo-troller. The last mentioned triode or grid glow-tube 340 is provided with a single grid 346. The dual-grid-tube 337 is provided with a cathode 347 and two grids 348, 349, one of which is connected through a 1 meg. non-inductive resistor to the grid 346 of the triode tube. Both of the grids of the dual-grid-tube are connected to the power input derived through suitable secondaries, rectifiers, and inductances, and so arranged that while the light sensitive surface of the light responsive device 329 is illuminated, the grid-cathode voltage becomes more negative than the grid-plate, and the current flow through the tube decreases.

Consequently grids 346 and 348 are then more negative with respect to the cathodes, and current flow to the solenoid does not take place; but when the shadow from the dark spot on the web lessens the light on the light sensitive surface, the grid-cathode voltage of the tube 337 becomes more positive and flow of current from secondary 345 is permitted, and if the commutators and brushes are closing the circuit, the current becomes effective upon the solenoid.

It will accordingly be seen that when the dark spot is in proper registration, the commutators and brushes serve to interrupt the circuit to the solenoid, but when the dark spots are lagging, the commutators no longer interrupt the circuit and then when the dark spot becomes effective on the light sensitive surface tube 340, is conductive to the power supply current induced by secondary 345, and that current, thus permitted to pass by the relay, finds the circuit through the commutators closed and accordingly flows through the solenoid. In this way, the pawl is released by the detaining shelf and actuates the ratchets. But it should be added, that the photo-troller and its briefly described circuit constitute only one example of possible relays or circuits for relay purposes.

Reference was heretofore made, in describing the train of driving gears, to a clutch driving gear 287 diagonally to the rear and upward of the first idler gear driven from the main wide driving gear 284 of this section F still being described. With respect thereto, attention is now directed to Fig. 28 more particularly, and also to Figs. 25 and 26. Said clutch driving gear is rotatably mounted outside the housing 253 on a projecting portion of a rod 350 which extends crosswise of the machine and supported by both housings. Between the housings said rod carries belt-tight-

eners 351 arranged to apply tension to the rear belts or conveyors 270. These belt tighteners are essentially arms secured to the rod and adapted to be swung by hand until the belts are tight and then held fast by suitable means, illustrative of which we have shown set screw 352 in the housing engaging the rod.

At the outside of clutch driving gear 287, also rotatable on said rod but fixed with respect to said gear, is a driving clutch plate 353. Beyond this driving plate is a driven plate 354 fast with respect to a driven clutch gear 355, both the driven plate and gear being rotatable on the rod. Beyond this outer or driven gear 355, the rod is screw threaded and receives a hand wheel 356, correspondingly threaded and mounted on the screw threads of the rod. A compression spring 357 is situated on the rod and interposed between the hand wheel and a thrust bearing 358 carrying driven gear 355. The clutch plates may thus be kept in driving contact by the spring pressure applied by the screwing of hand wheel 356 inward, or may be released from driving pressure by turning the hand wheel outward and thereby relieving the spring pressure. The outer clutch driven gear 355 is in mesh with a gear 359 above it (see Fig. 25) which is upon the shaft 360 of advancing roller 271, situated crosswise of the machine between the reaches of conveyor 270. At the opposite end of roller 271 from said gear 359 and fast on shaft 360 is a gear 361 in mesh with a gear 362 on the shaft 363 of the other advancing roller 278 thereby effecting simultaneous equal rotation of both rollers 271 and 278. When a new web is to be fed through the machine, release of clutch plate 354 will enable these advancing rollers to be turned by hand and thereby obtain movement of the web until the proper registration is obtained with the cutter. In running operation, the clutch plates are in engagement and the advancing rollers driven in timed relation to the other instrumentalities.

Attention is now directed to the adhesive applying or pasting section D which is shown in Figures 1, 2, 4 and 5 in its association with the other sections and is shown in more detail in Figures 7 and 8 and Figures 18 to 24 inclusive. It will be remembered that the wrappers are delivered individually to this adhesive section either from the stack of wrappers emanating from label feeding section E or as wrappers cut from a web from the roll feed section F by way of guiding means 280 which passes the wrappers between large roller 279 and its co-operating friction wheels, the wrapper assuming a substantially horizontal position, although sloping slightly downward in substantial alignment with the feeding of the preformed wrappers from the stack of wrappers.

From inspection of Figures 4 and 5, it will be noted that a plurality or set of friction wheels 364 are provided on a cross shaft 365 at the feed end of the adhesive applying or pasting section D directly beneath the large roller 279. These friction wheels are spaced along the shaft so that the wrappers will be fed by the simultaneous movement of the roller and friction wheels. Successive cross shafts 366, 367 and 368 parallel to the said cross shaft 365 are provided at intervals therefrom and from each other to the discharge end of the adhesive section and at appropriate elevations to obtain the feeding of the wrappers in the substantially horizontal direction from the feed to the discharge end of the said section. These shafts all carry sets of friction wheels 364

with the same spacing of the friction wheels of each set on each shaft so that the corresponding or series of friction wheels on successive shafts have the wheels of each series aligned from the feed to discharge ends of the section. A way 370 is preferably provided (see Figs. 20-24) consisting of slats extending from the first set of friction wheels to a position beyond the last set, said slats being wider than the friction wheels and cut-away at the part thereof coinciding with the friction wheels for enabling the friction wheels to project through the slats, as shown in Figs. 19 and 20. The projecting of the friction wheels through the slats is sufficient to obtain driving contact with a wrapper moving upon the slats and such frictional contact, in addition to the slight slope of the way, will serve to advance the wrappers along the way. The said slats are shown supported by suitable cross bars 371 forming part of the way construction. If so desired, the slats may be made sectional from end to end with each cross bar supporting a section of the slat and the meeting ends of the sections tapered for enabling each section to teeter slightly with respect to adjacent sections. The tapering at the ends insures that the teetering cannot introduce any obstructing end in the path of movement of the wrapper. The cross bars may be carried at their ends by dowels or pins 372 inserted longitudinally of the cross bars, thereby acting as trunnions, said pins being mounted in the side housings 373 of this section E of the machine now being described. Certain ones of the cross bars may have resilient means, such as springs 374 applied thereto for actuating the same to return the slat sections to their upper or normal position or as far as the bevels on the ends thereof will permit them to swing resultant upon engagement of those bevels with the bevels of the next adjacent slat sections.

As above described, the set of friction wheels 364 on the first cross shaft underlie the large feed roller 279. Similarly the successive sets of friction wheels on the successive cross shafts 366, 367 and 368, engage upwardly against cooperating friction wheels 375 situated above the way. These cooperating friction wheels are similarly in series from the feed to discharge end of the section of the machine so that each upper friction wheel is directly over and in contact with an under friction wheel. We also wish to make it clear that the several friction wheels constituting a "series" are on successive shafts whereas the several friction wheels constituting a "set" are upon a single shaft, and a "pair" of friction wheels refers to one wheel on a lower shaft and one wheel on an upper shaft which are in contact with each other. It will accordingly be seen that the shafts for the upper and lower friction wheels are arranged in pairs.

It is within the scope of the present invention to provide for a vertical displacement of the upper friction wheels for any or all sets heretofore mentioned. As illustrative of this feature, we have shown the final set of upper friction wheels (see Fig. 18) carried upon a shaft 368, the end bearings for which are situated between vertical guideways 376. The said bearings are provided with vertically disposed rods 377 and are normally held depressed by springs 378. The rods extend above the guideways and have nuts 379 adjustably situated thereat for receiving the forked end of a lifting arm 380 thereunder. This arm projects horizontally from a rocker shaft 381 (see Fig. 7 in conjunction with Fig. 18) and this rocker shaft

in turn is provided with an upwardly extending arm 382 connected to a link 383 which extends rearwardly and has a forked head 384 at its rear end which slideably rides upon a cam shaft 385, transverse thereto, said cam shaft extending crosswise of the machine. Next the said forked head 384 is a cam 386 having a properly shaped outer periphery which is in constant engagement with a roller 387 projecting from the side of said forked head. As the cam rotates, the peripheral cam surface pushes the link 383 forward and depresses lifting arm 380 thereby enabling spring 378 to depress the bearing of the friction wheels. At the moment of introduction of the wrapper beneath the friction wheels, the said wheels may be lifted, and for that purpose the cam surface has a depression enabling the link to retract under influence of a spring or other suitable means for that purpose. As soon as the forward edge of the wrapper is inserted beneath the set of friction wheels, the cam surface is arranged to thereupon push the link forward and obtain a depression of the friction rollers into engagement with the wrapper and feed it forward in conjunction with the under set of friction rollers after which the upper set is again lifted to receive the next wrapper.

Crosswise of the machine section D and beneath the way are a plurality of glue pots 390 shown in Figure 20 as having a fluid adhesive 391 therein. It will also be observed that there are preferably two glue pots, one situated between the first and second sets of lower friction wheels whereas the next glue pot is situated between the second and third sets of lower friction wheels. Adhesive applying wheels 392 dip into these glue pots, said wheels being situated so that the upper part of their peripheries will be slightly below the normal position of the supporting surface of the way. A depression of the wrapper which also preferably includes a depression of the way, is therefore required to make the wrapper contact with the adhesive bearing surface of the adhesive applying wheels. As indicated in Figures 21 to 23, more especially, the adhesive applying wheels are preferably arranged in pairs of wheels side by side and each pair situated between two slats of the way so that the said adhesive applying wheels are not aligned with the friction feeding wheels. Said adhesive applying wheels are mounted upon shafts 393 parallel to the shafts supporting the several sets of friction wheels. The depressible slat section construction above described is so arranged that the depressible portion of the slats are next the adhesive applying wheels.

It is the purpose of this section D of the machine to apply spots 394 of adhesive near each end of the underside of the wrapper. The sets of adhesive applying wheels and their respective shafts are therefore preferably spaced apart a distance sufficiently less than the length of the wrapper for enabling the adhesive spots to be applied next opposite ends of the wrapper all at the same time. Means are provided for depressing opposite ends of the wrapper simultaneously to engage the under surface of the wrapper with the peripheries of the adhesive applying wheels. This means is here shown as comprising a soft surfaced roller 395 over each set of adhesive applying wheels. Since there are two sets of adhesive applying wheels there are two of these soft surfaced rollers.

It will now be noted that projecting rearwardly from the spring-retumed cross bars 371, 75

parallel to the slat sections carried thereby, are intermediate slats 396 situated one between the wheels of each pair of adhesive-applying wheels, these intermediate slats having their top surface in the same plane as the top plane of the slat sections of the same supporting cross bar. Accordingly, the wrapper will be engaged at its underside closely adjacent the adhesive spots 394 and positively lifted out of contact from the periphery of the adhesive applying wheels when the soft surfaced rollers 395 are lifted. In the further advancement of the wrapper, those spots 394 contact no part of the machine, but are brought to the roll being wrapped without smearing, so the spots at the forward end of the wrapper are caused to adhere to the said roll and the rear spots will secure the trailing end, after encirclement of the roll, to the underlapping forward end of the wrapper.

It is preferable to support the glue pots upon a vertically movable table 397 which is shown as supported at its opposite sides next the housings upon vertical racks 398. At a lower part of the housings extends a crank shaft 399 having crank 400 at one end for manual operation and having pinions 401 in mesh with the racks. When desired to fill, empty, replace or adjust the glue pots, the table may be raised or lowered accordingly. It is also preferable to equip the glue pots with a comb-like top plate 402 extending forwardly from the rear upper edge thereof to the periphery of the adhesive applying wheels and extending between and adjacent to said wheels for scraping or otherwise eliminating excess adhesive from the wheels as the same rotate. While the periphery of the several adhesive applying wheels carry a continuous supply of adhesive at all times, yet the adhesive is only applied to the wrappers at the spots 394 during the interval of depression of the upper soft surfaced rollers 395.

Depression of the soft surfaced rollers 395 may be obtained in any suitable manner. As here shown, said rollers are each journaled at their ends in horizontally extending arms 403 of bell crank levers, said levers being journaled at their mid part upon the cross shaft for the upper set of rollers between the glue pots. There are two of these bell crank levers next each end of the said cross shaft so as to provide rearwardly extending arms on one pair of said levers and forwardly extending arms on the other pair of said levers thereby supporting one roller to the rear of said cross shaft and another roller forwardly of said cross shaft. The levers having the rearwardly extending horizontal arms have upwardly forwardly extending cam engaging arms 404 whereas the levers having the forwardly extending horizontal arms provide upwardly rearwardly extending cam engaging arms 405. Each of these arms 405, 405 is in engagement with a cam 406 (one for each arm) situated on cam shaft 385. The location of the cam engaging arms with respect to the cams and with respect to the rollers is such that a depression in the cams will permit the rollers to both drop by gravity (or under spring actuation, if so desired) substantially simultaneously when the depressions in the cams register with the engaging portion of the cam engaging arms. At other times, the rollers are positively held upwardly by virtue of the arms engaging the cams at parts of their peripheries having the greatest diameter.

The cam shaft, the friction wheel shafts and the adhesive-applying wheels are all preferably

actuated with positive drive means such as an appropriate train of gearing. This train of gearing may be followed through by consideration of the showing thereof in Figs. 7, 18 and 19. However, for purposes of tracing the actuation of the train of gearing from the source of power, reference will first be made to Figs. 1 and 4 where it will be observed that a motor or other suitable source of power 407 is situated in the base portion of section C of the machine. This motor, through a belt or other suitable connection 408 drives a pulley or the like 409 on a main drive shaft 410 extending between and journaled in the housings 75 of that section. On said shaft is a small gear in mesh with a gear 412 on the extended end portion of the same shaft 368 used for the last under set of friction wheels for advancing the wrapper. Section C of the machine is wider than the adhesive applying section D, and consequently this said shaft 368 has to project far enough to receive said gear 412 on the outside of the housing 75, of the section C. Next the housing 373 of the adhesive-applying section, said shaft has a smaller gear 413 thereon and this smaller gear is in mesh with a similar gear 414 immediately above it and situated on the upper set of friction wheels, it being remembered that this shaft is carried by vertically movable bearings between guideways 376. The said smaller gear 413 is also in mesh with a larger idler gear 415 at the side of housing 373. As shown in Figs. 7 and 18, more particularly, this larger idler gear is in mesh with another gear 416 on the next rearward shaft for another lower set of friction wheels. The said smaller gears having equal pitch diameters so as to rotate at equal speed. Said small gear 416 on this lower cross shaft is in mesh with a gear 417 of the same size on the upper friction wheel shaft. Also in mesh with lower gear 416 is another idler 418 which in turn is in mesh with a gear 419 on the next rearward upper friction wheel shaft situated between the glue pots and used as a trunnion for the bell crank lever. The gear 418 is also in mesh with a gear 420 on the glue pot shaft, that is to say, shaft 393 carrying the set of adhesive-applying wheels. Another idler gear 421 similar to idler 418 and situated to the rear of gear 419 carries the rotary motion to the next glue pot shaft 393 through the agency of an intermediate pinion 422 necessary for obtaining rotation of the adhesive-applying wheels in the right direction. The said idler 421 is in mesh with the gear 284 driving the large bottom roller 279 of section F. In the train of gearing a suitable gear connection is made for driving cam shaft 385. As here shown, there is a large gear 423 on the outer end of said cam shaft, this gear being in mesh with the aforementioned gear 419. (See Fig. 19.)

It is to be understood that it is preferable to pull the wrapper rather than to push it along the way. We have accordingly shown the forward soft surfaced roller 395 as gear driven and have omitted any gear driving of the rearward soft surfaced roller. For this purpose, a gear 424 is shown on the inside of each of the forwardly projecting horizontal bell crank arms 403 and fast upon the shaft on which said horizontal arms are trunnioned. These gears are each in mesh with an idler gear 425 on the respective horizontal arm and this idler is in turn in mesh with a gear 426 on the shaft for the soft

surfaced roller. All of the gears mentioned are of course properly proportioned in relationship to each other so as to obtain proper surface speed for the several wheels and rollers engaging the wrapper.

Reference has heretofore been made to presentation of the forward edge of wrapper 94 to the roll being wrapped while the roll is both being rotated on its own axis and carried upwardly in an orbital movement in section C of the machine, and illustrated more particularly in Figs. 40 and 41. It will now be observed in those figures that the forward ends of the slats forming the way 370 on which the wrapper is traveling forwardly across the adhesive applying section D, project forwardly beyond the most forwardly pairs of advancing friction wheels 364 and 375. At a distance below these forwardly projecting ends of the slats is situated a rocker shaft 430 cross-wise of the machine and journaled in forwardly directed brackets 431 from the housings 373 of the adhesive-applying section. Near opposite ends of this rocker shaft, at the inside of the brackets but situated beyond the uppermost slats of the way, are upwardly projecting arms 432 which can oscillate back and forth from the full line position to the dot and dash position, and vice versa, shown in Fig. 40 between the roll being wrapped and the said last mentioned pairs of friction advancing wheels. Said arms support between them a suitable cross-cleat 433 which is rigidly carried at its ends by said arms. This cross-cleat carries on its upper side a plurality of slats 434 and the parts are so arranged that when the said arms and cleat are in their forward position the upper surfaces of the slats form a continuation of the said way of the adhesive applying section. The rearward ends of these slats 434 are bifurcated for enabling the same to slide rearwardly at the sides of the respective slats of which they are a continuation, when these said continuations are swung upwardly rearward under control of the said arms. Accordingly the rear ends of these bifurcated slats are always at the level of or below the level of the forwardly projecting ends of the slats of the adhesive-applying section and the wrapper will consequently readily slide from the adhesive-applying section way to the extension slats 434 in all permitted positions of the extension slats. Next the outer ends of said arms 432 and rigidly carried thereby are U-shaped brackets 435, the base portion of the U secured flatwise against the inner side face of the arms. The leg portions of one U-bracket will accordingly be directed toward the leg portions of the other bracket at the other side of the machine. The leg portions of each bracket have bearing holes aligned therein for slidably receiving a rod 436 which projects forwardly toward the roll to be wrapped. This rod is impelled forwardly toward the roll by means of a spring 437 on the rod, said spring engaging at its forward end against a dog 438 secured to the rod between the legs of the U-bracket, and the other end of the spring being held from displacement by engagement with the rear leg of the bracket. At the forward end of each rod is a head 439 from which projects a bearing rod 440 extending in a direction toward the other bearing rod and aligned therewith. The bearing rods each having roller bearings 441 inwardly from the head and mounted upon these roller bearings and extending crosswise of the ma-

chine from one bearing to the other is a pressure roller 442. This pressure roller is adapted to engage the outer periphery of the roll being wrapped and is situated closely adjacent the forward ends of the extension slats 434 carried by the arms 432. Since said slats and pressure roller are all carried by said arms, they will swing simultaneously when the arms swing and accordingly retain a substantially constant relation with respect to each other. A wrapper feeding forwardly on the way continues toward the roll to be wrapped by a movement substantially in a plane from the way 370 until said wrapper comes into contact with the roll to be wrapped, the parts then being in full line positions of Fig. 40. Since the forward part of the wrapper has adhesive spots upon it and since the wrapper is still being fed forwardly by the most forwardly friction wheels, and since the roller is at this time beginning its rotary motion, the wrapper will adhere to the surface of the roll and be drawn thereby under the pressure roller 442. However, the roll is moving upwardly in its orbital movement, as well as rotating upon its own axis and therefore the adhesion of the wrapper to the roller exerts a pull upon the wrapper thereby causing the wrapper to rotate with the roll. At the same time the pressure roller maintains close contact of the wrapper with the roll and the upward movement of the roll, pressing against the pressure roller swings that roller and its supporting arms rearwardly to the dot and dash position of Fig. 40. When the full amplitude of swing of said arms has been reached, the wrapper has made a complete turn around the roll and the trailing portion of the wrapper then overlaps the forward portion and the pressure roller has caused the adhesive on the trailing end of the wrapper to adhere to the overlapped forward portion. As soon as this particular roll has passed the pressure roller, the arms are no longer pushed back but are free then to swing down for engaging the pressure roller with the next following roll to be wrapped.

Preferably the said arms are under a spring actuation for keeping them swung toward the roll being wrapped and for returning them to the initial roll engaging position. For this purpose, springs 443 are shown encircling rocker shaft 430 next the arms 432 with the ends of the springs respectively engaging the arms and engaging collars 444 on the rocker shaft. The lower ends of the arms extend beyond the rocker shaft and are provided with adjustable stop screws 445 which engage a tie rod 446 extending crosswise of the machine between the housings to limit the swing of the arms toward the roll to be wrapped. Also on the rocker shaft 430 at one end thereof beyond the bracket 431 is a cam engaging arm 447, the outer end of which has a slot 448 for adjustably mounting a cam engaging roller 449. A cam 450 is carried at the end of a cam shaft 451 and by virtue of this cam, the arms 432 may be swung positively back and forth relying upon springs 431 and 443 to exert the necessary pressure against the roll being wrapped. The cam engaging roller is held against the periphery of the cam by a suitable spring 452 attached to the cam arm and tensioned from suitable engagement at its other end with a fixed part of the motion.

It is now pointed out that the motor 407 herefore described as situated in the lower part of

the housing of section C drives cam shaft 451 by appropriate train of gearing. It is also pointed out at this time that motor 407 also drives the rotor of section C by a suitable train of gears.

5 Next the belt pulleys 409 is situated a sprocket wheel over which passes a chain 501 for purposes of driving a sprocket 502 at the forward side of section C. This last mentioned sprocket is upon a shaft 503 (see Fig. 54) extending across the machine and provided with a bevel gear 504 at its other end. This bevel gear is a main driving gear for the part of the mechanism comprising section B of the machine. Said bevel gear is in mesh with a smaller bevel gear 505 on the rear end of a shaft 506 which is accordingly a continuously rotating shaft synchronized with the rotation of the rotor as well as the feeding of the wrappers and coordinated parts. In the forwardly extending portion of this shaft is shown a universal transmission portion 506' so that the most forwardly part of the shaft 506' is at a higher elevation than the first mentioned portion having the bevel gear. An appropriate bearing 507 is provided for the rear portion of the shaft and another bearing 508 is provided for the forward portion of the shaft. At the forward part of this shaft portion 506' next the bearing is carried a Geneva lock member 509. Also on the shaft section 506' to the rear of said Geneva lock member is situated an eccentric 510, and to the rear of the eccentric also on the same shaft section is a sprocket wheel 511 to be hereinafter described. Above the shaft section 506' carried in a bearing above bearing 508 is a short shaft 512. The end of this shaft projecting over the Geneva lock member has a driven gear 513 with four evenly spaced arcuate hollows in its periphery for engagement by the lock member 509. This driven Geneva gear accordingly has an intermittent rotation, making a quarter turn for each revolution of the lock member. Actuation of the driven Geneva gear 513 is obtained in any suitable manner. As here shown a ratchet wheel 514 is secured next to the said driven Geneva gear and is provided with four ratchets corresponding to the four hollows in the Geneva gear as to location. A pawl 515 is carried upon an arm 516 trunnioned on the short shaft 512 carrying the Geneva driven gear and ratchet wheel. The pawl is pressed toward the ratchet wheel by a spring 517. The arm 516 is oscillated an amount equivalent to a quarter turn of the ratchet wheel by means of a connective link 518 from an eccentric band 519 around the aforementioned eccentric 510 on the forward portion 506' of the end shaft.

60 On said short shaft 512 at the other side of bearing 508 from the Geneva movement, is a transfer wheel 520 for the roll to be delivered to the wrapping part of the machine. This transfer wheel provides a plurality of radiating mandrels 521 of appropriate size and shape to receive the rolls upon the free outer receiving end thereof. The mandrels are located evenly around the wheel so as to provide a mandrel corresponding to each hollow of the Geneva driven gear. The normal position of the mandrel accordingly will be either horizontal or vertical when the wheel is held at rest. The rolls are applied to a mandrel projecting away from section B, and when that mandrel passes upwardly and then downwardly to its other horizontal position directed toward section B, the roll is then removed from the

mandrel onto the conveyor by which it is introduced to the rotor of section B.

Further reference and description of the transfer mechanism and conveyor will be given hereinafter.

It is desirable at this time to enter upon a description of the means for applying the rolls one at a time to the mandrels as each mandrel swings up to its horizontal position. The rolls are transmitted end to end toward the mandrel with the axis of the cores of the rolls substantially aligned with the horizontally positioned mandrel. As more particularly indicated in Fig. 57, the rolls are situated within a trough 522, the bottom of which, substantially as far as the mandrel transfer wheel 520, is the upper reach of a belt conveyor 523. This belt conveyor is given a step by step forward motion to advance the rolls towards the mandrel.

For the purpose mentioned, we provide a motor 524, which, through the intervention of suitable reduction gears (not shown) contained in gear box 525 continuously drives a pulley wheel 526 in turn connected by a belt 527 to a pulley 528 rotatable upon the forward conveyor drive shaft 529. This pulley 528 is fast with respect to a driving clutch member 530. The clutch member and pulley accordingly act as a unit and are suitably equipped with thrust bearing 531 and roller bearing 532 to render the same freely rotatable upon the shaft and with respect to the supporting bearing 533 for the said shaft. Next driving clutch member 530 is a driven clutch 534 slidably keyed upon the shaft so as to rotate with the shaft but movable into engagement with or out of engagement from the driven clutch member. Next beyond the driving clutch member is a thrust bearing 535 and a sleeve 536 both directly upon the shaft. Around the thrust bearing and sleeve is situated a rotatable entity consisting of a cam 537 next the clutch member, a sprocket wheel 538 beyond the cam and beyond the cam a disc cam 539 having its cam face directed longitudinally of the shaft away from the sprocket. The cam 537, sprocket 528 and disc cam 539 are secured together by screw bolts 540 parallel to the shaft and offset therefrom. Next beyond this disc cam is a cooperating plate cam 541 which is pressed toward the disc cam by springs 542, situated between the said plate cam and a fixed end plate 543. By virtue of this construction, and by employing diametrical opposite cam surfaces on the disc cam and on the plate cam, every rotation of the sprocket and attached disc cam will obtain two impulses moving the driven clutch member 534 longitudinally of the shaft toward the driving clutch member 530 for obtaining thereby intermittent rotation of the driven clutch member 534 and the conveyor drive shaft 529. Rotation of the sprocket wheel and connected parts is obtained by a sprocket chain 538' extending to the heretofore mentioned sprocket wheel 511 on the forward portion 506' of shaft 506. It will accordingly be seen that the intermittent engagement of the clutch members 530 and 534 is obtained in timed relationship to the operation of the wrapping section of the machine and under control of the wrapping section of the machine and under control of the motor 507 driving that section of the machine whereas the actual driving and rotation of the conveyor shaft for the section A is obtained by its own motor 524.

As may be noted from inspection of Figs. 63 and 64, driven clutch member 534 has a reduced annular shoulder 544 toward the adjacent cam 537. This shoulder slidably receives the forked end of a pitman 545 which is held against lateral displacement by its location between the cam and clutch member. A roller 546 trunnioned on the pitman adjacent the periphery of the cam rides on the peripheral surface of the cam and thereby functions to operate the pitman longitudinally. The upper end of the pitman is pivoted at 547 to a crank arm 548 projecting outwardly from and secured to a rocker shaft 549 extending longitudinally of trough 522 next an upper edge thereof. As indicated in Figs. 57 and 63, a plurality of tappers 550 are secured at intervals along the rocker shaft and extend over the adjacent edge of the trough and bend downwardly for intermittent tapping of the rolls as they feed along the trough. The purpose of these tappers is to keep the rolls from sticking together or from binding within the trough. One or more arms 551 may be secured to the rocker shaft and act against compression springs 552 situated upon rods 553 projecting from the upper edge of the trough in order to normally lift the tappers and to hold the roller of the pitman against the cam.

Automatic stops for shutting down the entire machine by cutting off the electric power to the motors may be provided in association with the trough, as indicated in Fig. 57. Near the entrance end of the trough or at some other convenient part thereof, may be situated a feeler 554 which is in the nature of a pivoted plate adapted to ride upon the top of the rolls as they travel along the conveyor in the trough. When the rolls cease to be supplied to the trough, the feeler will drop down and in doing so operates a switch or switch relay for shutting off the power to the machine.

At the forward end of the trough above the same is situated another detector plate 555 also riding upon the top of the rolls and in engagement with the next roll to be transferred to the transfer wheel. The purpose of this detector plate is to shut off the electric power to the entire machine in event the roll under the plate sticks to the roll next in advance thereof to such an extent that it moves upwardly when the transfer wheel begins to rotate to carry the roll on the mandrel upwardly. This detector plate is normally supported by pins or other devices to keep it from dropping downwardly into the trough and from the top of the plate is attached any suitable connection 556 to a switch or other relay 557 whereby any material movement of the said plate upwardly from its supported position will operate the switch to open the same and shut off the power.

At the forward end of the trough, (see Fig. 55) in substantial continuation of the level portion of the conveyor is provided a fixed bottom 558 for the trough substantially at the level of the said reach of the conveyor so as to receive and support the rolls at their most forward position beyond the end of the conveyor. Preferably this fixed bottom is split longitudinally and tapers from the rear end thereof next the side walls of the trough inwardly of the trough so as to enable the rolls to readily ride from the conveyor onto the said fixed bottom. To avoid any hindrance by catching of the forward lower peripheral edge of the roll, the tapered edges do not

quite meet at the middle. The outer end of the fixed bottom has a wider opening sufficient to pass the transfer wheel therethrough. Furthermore, as indicated, the side walls of the trough may be provided with fillers 559 next the forward end portion of the trough, or other suitable means for narrowing the trough and hold the rolls more positively than in the wider portion of the trough toward the end where the rolls are introduced. Of course, these fillers must taper so as to avoid any deterring shoulder to the advancing of the rollers.

It is also desired in connection with the application of the most forward roll upon the mandrel to advance the same by the intermittent push of the conveyor less than the entire distance home upon the mandrel and to thereafter permit further entry of the roll upon the mandrel as the transfer wheel begins to rotate, thereby preventing any binding of the lower outer edge of the roll against the next succeeding roll. This object is accomplished by situating a stop 560 (Fig. 54) at each side of the transfer wheel next the forward end of the trough. The particular stop here shown comprises a piece of angle iron stood vertically, one on each side of the wheel and hinged at 561 (Fig. 57) to a bracket 562 below the bottom of the trough. One flange of the angle iron is directed forwardly next the wheel and the other flange is directed laterally outwardly of the trough and wheel. The forward edge of the forwardly directed flange engages a pin 563 projecting laterally from the mandrel near its base when the mandrel is in normal roll-receiving position. Above the normal engaging position of this pin 563 the forward flange of the angle iron is stepped back, as at 564. Consequently, as the wheel begins to rotate the pin 563 arrives opposite the stepped back portion 564 thus permitting the angle iron stop to swing forward an equivalent amount. Consequently, the roll is enabled to move forwardly this additional amount and this clears the rear end of the roll from the next succeeding roll. The angle iron stop is prevented from swinging further than the amplitude of swing just mentioned by provision of any suitable detent 565 shown in Fig. 54 secured at the forward side edges of the trough.

After the roll is situated on a mandrel from the trough 522, the transfer wheel 520 by virtue of the Geneva movement heretofore described, makes a turn of 90°. That situates the roll mentioned in an upward position as indicated at the top of Fig. 57 and the roll accordingly seats at its lower end against another lateral pin 563' similar to but inward from the pin heretofore mentioned. The previously applied roll on the next forward mandrel is now in a horizontal position diametrically opposite from the feeding trough. It is while the wheel is holding the roll in this position that the roll is removed from the mandrel and placed upon a conveyor 566 for feeding the same to the main wrapping section. This conveyor 566 of the wrapping section is moving at right angles to the trough and to the plane of rotation of the transfer wheel. Between the periphery of the transfer wheel and the said conveyor 566 is a suitable ledge 567 (Fig. 59) or other suitable means to support the roll in its passage from the mandrel to the conveyor. In order to transfer the roll from the mandrel onto the conveyor a reciprocating carriage 568 is provided immediately beneath the upper reach of the said conveyor 566 supported and guided by suitable tracks 569. From this carriage extends

5 rearwardly towards the transfer wheel a horizontal forked arm 570 the extreme ends of which are bent upwardly to substantially the elevation of the mandrel from which the roll is to be removed. This carriage and the said forked arms are in this most rearward position as the transfer wheel rotates to bring the roll down to its horizontal position and accordingly the upwardly extending portions of the forked arms are behind the rearward end of the roll when it arrives at its horizontal position. By a suitable driving connection, the carriage is then slid forwardly and in doing so pulls the roll from the mandrel onto the ledge and then onto the upper reach of the said conveyor 566. Thereupon the carriage returns to its rearward position ready to receive and transfer the next roll.

20 The precise means for operating the carriage back and forth, as here illustrated, consists of a first class lever 571 with a long arm next to and extending transversely from the carriage beneath the upper reach of the conveyor, the said arm having a slot and pin connection with the carriage to accommodate the variation between the centers as the lever swings. The short end of the said lever 571 is connected by a pitman 572 which rides upon the shaft 506 next a cam 574 upon that shaft. A roller 575 on the pitman head 573 engages the peripheral cam surface of said cam and thereby swings the lever and operates the carriage in timed relationship to the operation of the wrapping section of the machine.

25 As indicated in Figs. 59 and 62, the roll, when received from the mandrel onto the conveyor, is inserted beneath a runner 576 which has an upturned end toward the approaching roll so as to enable the same to slide under the runner. The runner is spring supported next its ends so as to both receive the roll and to obtain a desired frictional engagement therewith at the time of entry of the roll so as to keep the roll from twisting while being introduced upon the conveyor. At the sides of the conveyor at a proper elevation above the same, are longitudinal guide rails 577 to keep the roll from endwise displacement as it travels along the conveyor. Above the conveyor is a loose sprocket chain 578 (Figure 56) extending in the same general direction as the conveyor and with its lower reach moving in the same direction as the upper reach of the conveyor, but at a greater speed. The action of this sprocket chain will accordingly be to roll the roll forwardly upon the conveyor. Said conveyor is equipped with a plurality of upstanding flights 579 at intervals along the same, and by virtue of the action of the said sprocket chain the roll is brought substantially against the rear face of one of these flights. As the conveyor approaches the wrapping machine spider, it is given a downward trend so the roll will be brought by gravity into surface engagement with the rear side of the flight. As the conveyor flight and the spider of the wrapping machine are operated in timed relationship, the roll is thus brought precisely to the desired position for insertion of the stud shanks 81 of the wrapping machine into core 80 of the roll.

30 70 It may be here noted in Figure 56 that the conveyor 577 having flights 579 is preferably of a link chain construction and its upper reach operates upon a supporting track 580. The forward end of this conveyor is mounted upon a sprocket wheel 581. This sprocket wheel is upon a shaft 582 on which is another sprocket 583 having a

chain 584 driving the same from a sprocket on heretofore described shaft 503. Actuation of the loose advancing sprocket chain 578 is secured by means of a sprocket chain 585 through the agency of appropriate sprockets and gear connections from the rear shaft 586 for the conveyor.

We claim:

1. A machine of the character described comprising in combination with a wrapping mechanism for rolls, means for supporting said rolls axially thereof, means for moving the roll bodily in an orbital path, means for simultaneously rotating a roll upon its axis during a portion of its movement through the orbital path to receive a wrapper a way for sliding a wrapper in flatwise condition toward said rotating roll at the leading end of the path where the rolls rotate, the forward end of said way being movable upwardly to follow the orbital path of the roll, and a roller movably supported to follow the said orbital path of the roll and remain adjacent the said forward end of the way as the same moves, said roller engaging the wrapper upon the roll and winding the wrapper around the roll as the roll rotates.

2. A machine of the character described comprising in combination with a wrapping mechanism for rolls, means for supporting said rolls axially thereof, means for moving the roll bodily in an orbital path, means for simultaneously rotating a roll upon its axis during movement through a part of the orbital path to receive a wrapper a way for sliding a wrapper in flatwise condition toward said rotating roll, the forward end of said way being movable upwardly to follow the orbital path of the roll, means for applying adhesive to the underside of the wrapper while on the way, and a roller movably supported to follow the said orbital path of the roll and remain adjacent the said forward end of the way as the same moves, said roller engaging the wrapper upon the roll and winding the wrapper around the roll as the roll rotates.

3. A machine of the character described comprising in combination with a wrapping mechanism for rolls, means for supporting said rolls axially thereof, means for simultaneously rotating a roll upon its axis and moving the roll bodily in an orbital path, a way for sliding a wrapper in flatwise condition toward said rotating roll, the forward end of said way being movable upwardly to follow the orbital path of the roll, means for depressing the wrapper while on the way near the forward and trailing edges of the wrapper, adhesive applying wheels beneath the depressing means for applying spots of adhesive to the underside of the said wrapper at depressed parts thereof, and a roller movably supported to follow the said orbital path of the roll and remain adjacent the said forward end of the way as the same moves, said roller engaging the wrapper upon the roll and winding the wrapper around the roll as the roll rotates.

4. In a machine for wrapping paper rolls, the combination with roll conveying means, of a rotary drum and chucks carried thereby moving through a circular path, means operating the chucks to pick the rolls from the conveying means by engaging in the ends of the core of each roll and supporting the same axially thereof, means for rotating the supporting chucks during their movement through a part of its circular path to rotate the roll and receive a wrapper and wind it about the roll, further carrying means traveling with the supporting chucks and relieving the same of their supporting function beyond

the rotating stage where the wrapper is applied, further means moving with the supporting chucks and operating upon release thereof to fold the ends of the wrapper about the ends of the roll, said means for moving the chucks into supporting position returning the first mentioned supporting means to their initial supporting position to tuck in the ends of the folded wrapper ends into the core of the roll.

5. In a high speed machine for wrapping paper rolls having axial center openings, a pair of chucks, a continuously revolving drum means mounting the chucks in the drum whereby they are axially movable to insert and withdraw themselves into and from the opening of the roll and rotatable to rotate the roll during a portion of their orbital travel with the drum, means to cause the chucks and roll to rotate during their travel through said portion of the orbital path traversed thereby, means carried by the drum to apply a wrapper and allow it to wind about the roll while rotating and to hold said roll as the chucks are withdrawn, means carried by the drum to crimp the ends of the wrapper projecting beyond the roll, and further means to reciprocate the chucks whereby the same are withdrawn from the roll opening to permit operation of the crimping means and thereafter reinserted against the crimped wrapper ends to tuck them into the opening.

6. A wrapping machine, as claimed in claim 1, in which the means for moving the rolls in an orbital path comprises a drum of axially spaced wheels in the peripheral portions of which the roll supporting means are mounted, and the means for rotating the supporting means comprise fixed curved racks concentric with the wheels and projecting a predetermined distance about the periphery thereof, and pinion gears carried by each supporting means to engage with and be rotated over said racks as the drum revolves.

7. A wrapping machine as claimed in claim 3, including means for feeding rolls to the wrapping mechanism comprising a conveyor for rolls having flights spaced apart a distance equal to a distance between the means for supporting the rolls, means for synchronizing the speed of the conveyor with that of the means for moving the roll supporting means, and a second conveyor disposed over the first conveyor and operating in the direction of and at a speed greater than the first conveyor, whereby rolls disposed between the flights of the first conveyor are in contact with the overhead conveyor and are advanced over the first conveyor by the increased speed of the second until the rolls engage against the forward flights whereby each roll is disposed in correct position to be received by the supporting means of the wrapping mechanism.

8. A machine of the character described comprising a wrapper mechanism for rolls having cores, a rotary support, a pair of studs carried by said support and means to insert the studs into and to withdraw them from the opposite ends of the cores, means to present a wrapper to the roll, means to rotate the studs about their axes for rotating the cores and rolls for applying the wrapper thereto, the withdrawal of said studs being timed to take place after the wrapper is rolled on the roll, means for gripping the rolls peripherally before withdrawal of the studs and, means operating while the studs are being withdrawn to crimp the wrapper at the ends of the roll.

9. A machine of the character described comprising a wrapper mechanism for rolls having cores, a continuously rotating support, a pair of studs carried by said support and insertable at opposite ends of the cores, means to present a wrapper to the roll, means to rotate the studs about their axes for rotating the cores and rolls for applying the wrapper thereto, means for thereafter gripping the rolls peripherally thereof, and means for inserting the studs and thereafter withdrawing the studs from the core after the roll is gripped and for reinserting the studs into the wrapper ends for tucking the same into the ends of the core.

10. A machine of the character described comprising in combination with a wrapping mechanism for rolls, a rotary drum, means carried by the drum for supporting said rolls axially thereof and carrying them through an orbital path, means for rotating said rolls upon their axes simultaneously with the movement thereof through only a portion of the orbital path, and a wrapper applying means operated during rotation of the rolls to wrap a wrapper about each roll while the roll is rotating.

11. A machine of the character described comprising in combination with a wrapping mechanism for rolls, rotary means for supporting said

rolls axially thereof, means in the path of movement of the rotary means for operating the latter and rotating said rolls upon their axes in the first means during part of the rotary movement thereof to receive a wrapper, and a roller pressing towards the roll, rotation of the roll with engagement of said roller against the wrapper, carrying the wrapper around the roll with the trailing end of the wrapper brought to overlapping position upon the forward edge and with ends projecting beyond the ends of the rolls, and a crimping mechanism brought into operation following application of wrapper to fold in the projecting ends of the latter against the roll.

15 12. A machine of the character described comprising in combination with a wrapping mechanism for rolls, means for releasably supporting said rolls axially thereof, means for continuously moving the first means through an orbital path and means for simultaneously rotating each roll upon its axis during movement of the roll through a portion only of the orbital path to receive and make possible the application of a wrapper to be applied to said roll while the roll is both rotating and moving in the orbital path.
